1

3,184,583

BOWLING GAME SCORING APPARATUS
Charles E. Bawtinheimer, 2805 Ronan St., Midland, Mich.
Filed May 25, 1961, Ser. No. 112,662
38 Claims. (Cl. 235—92)

This invention relates to semi-automatic bowling game scoring apparatus and more particularly to an electro-mechanical device which is capable of registering, frame by frame, the score of each of a number of players as well as the sum of the points scored in each preceding frame.

The scoring of a bowling game begins with the recording in the first frame of the number of pins knocked down by a particular player, except in those instances where all of the pins are knocked down on the rolling of either the first or the second ball. When all of the pins are knocked down, one of two symbols indicating, respectively, a spare or a strike is recorded and the score for the first frame is not recorded until the number of pins knocked down by the following one or two balls is determined. When a player has completed the game, his final score will be the summation of all of the pins knocked down by him and the summation usually is carried forward frame by frame so that at any given time the player knows his total score. By the use of the strike and spare marks, any question concerning the summation of the player's score may be reviewed and for this reason it is important that each frame indicate only the summation of the player's score up to that point.

A principal object of this invention is to provide a semi-automatic bowling game scoring apparatus which permits scoring of a game in a manner corresponding to manual scoring.

Another object of the invention is to provide a semi-automatic scoring machine which is adapted for use in conjunction with team play where the team members alternately bowl on different alleys.

A further object of the invention is to provide bowling game scoring apparatus of the kind referred to which is capable of maintaining a running total of the whole team's score.

Another object of the invention is to provide a semi-automatic scoring machine which may be conditioned to record the score of a player, but which may not be actuated until an opponent or neutral observer concurs with the score proposed to be recorded by the player.

Another object of the invention is to provide bowling scoring apparatus of the kind described which permits the adding of handicap points to a team's score.

Other objects and advantages of the invention will be pointed out specifically or will become apparent from the description when it is considered in conjunction with the appended claims and the accompanying drawings, in which:

FIGURE 1 is a fragmentary, side elevational view of a control panel forming part of the invention and installed adjacent a ball return rack of a bowling alley;

FIGURE 2 is a fragmentary, enlarged, front elevational view of the control panel;

FIGURE 3 is an elevational view of one of the switch mechanisms located within the control panel;

FIGURE 4 is a sectional view taken on the line 4—4 of FIGURE 3;

FIGURE 5 is a sectional view taken on the line 5—5 of FIGURE 3;

FIGURE 6 is an isometric view of a housing in which the scoring mechanism is contained;

FIGURE 7 is a horizontal sectional view through the housing and illustrating a portion of the scoring mechanism adjacent the left hand end of the housing;

2

FIGURE 8 is a view similar to FIGURE 7, but illustrating the scoring mechanism adjacent the central section of the housing;

FIGURE 9 is a view similar to FIGURE 7, but illustrating a portion of the scoring mechanism adjacent the right hand end of the housing;

FIGURE 10 is a vertical section through the housing and fragmentarily illustrating a portion of the scoring mechanism;

10 FIGURE 11 is a fragmentary isometric view of a portion of the scoring mechanism looking from the rear of the housing towards the front;

FIGURE 12 is an enlarged view of a portion of the apparatus shown in FIGURE 10;

15 FIGURES 13 and 14 are sectional views taken on the lines 13—13 and 14—14, respectively, of FIGURE 12;

FIGURE 15 is an elevation of one side of one of the reels illustrated in FIGURE 11;

20 FIGURE 16 is a view of the other side of the reel shown in FIGURE 15;

FIGURE 17 is a sectional view taken on the line 17—17 of FIGURE 16;

25 FIGURE 18 is a view looking from front to rear of the housing and taken generally on the line 18—18 of FIGURE 10;

FIGURE 19 is a sectional view taken on the line 19—19 of FIGURE 18;

FIGURE 20 is a sectional view taken on the line 20—20 of FIGURE 19;

30 FIGURE 21 is a sectional view taken on the line 21—21 of FIGURE 19;

FIGURE 22 is an enlarged, fragmentary, elevational view of a portion of the apparatus shown at the lower left hand end of FIGURE 18;

35 FIGURE 23 is a view similar to FIGURE 22, but illustrating the apparatus located at the lower right hand end of FIGURE 18;

FIGURES 24 and 25 are sectional views taken on the line 24—24 and 25—25, respectively, of FIGURES 22 and 23;

40 FIGURES 26 and 27 are sectional views taken on the lines 26—26 and 27—27, respectively, of FIGURE 18;

FIGURE 28 is an elevational view of operating pull bars located at the rear of the housing;

45 FIGURE 29 is a top view, partly in section, of a cam shaft extending the length of the housing;

FIGURE 30 is an elevational view of each of the cams mounted on the cam shafts shown in FIGURE 29;

50 FIGURE 31 is a sectional view taken on the line 31—31 of FIGURE 29;

FIGURE 32 is a view taken on the line 32—32 of FIGURE 29;

55 FIGURE 33 is a sectional view taken on the line 33—33 of FIGURE 29;

FIGURE 34 is a fragmentary, elevational view of apparatus for recording a strike or a spare and located adjacent the front wall of the housing;

60 FIGURE 35 is a top plan view, partly in section, illustrating a portion of the apparatus shown in FIGURE 34;

FIGURE 36 is a top plan view, partly in section, illustrating the apparatus for actuating the mechanism shown in FIGURES 34 and 35;

FIGURE 37 is a sectional view taken on the line 37—37 of FIGURE 36;

65 FIGURE 38 is a sectional view taken on the line 38—38 of FIGURE 36;

FIGURE 39 is a sectional view taken on the line 39—39 of FIGURE 36;

70 FIGURE 40 is a sectional view taken on the line 40—40 of FIGURE 36;

FIGURE 41 is a sectional view taken on the line 41—41 of FIGURE 36;

FIGURE 42 is a sectional view taken on the line 42—42 of FIGURE 36;

FIGURE 43 is a sectional view taken on the line 43—43 of FIGURE 36;

FIGURE 44 is a top plan view, partly in section, of apparatus adapted for use in the scoring of strikes and spares;

FIGURE 45 is a view of a spare memory unit and taken on the line 45—45 of FIGURE 44;

FIGURE 46 is a view of a strike memory unit taken on the line 46—46 of FIGURE 44;

FIGURE 47 is a view of a back-off unit and taken on the line 47—47 of FIGURE 44;

FIGURE 48 is a view of a control unit and taken on the line 48—48 of FIGURE 44;

FIGURE 49 is a somewhat diagrammatic view, partly in section, illustrating a team total recording unit and its association with a pin fall registering device;

FIGURE 50 is a plan view, partly in section, of a team total unit;

FIGURE 51 is a sectional view taken on the line 51—51 of FIGURE 50;

FIGURE 52 is a sectional view illustrating a contact carrying disk of which there are two located in the control panel, the section being taken on the line 52—52 of FIGURE 53;

FIGURE 53 is a fragmentary plan view of apparatus used in association with the disk shown in FIGURE 52;

FIGURE 54 is a sectional view taken on the line 54—54 of FIGURE 53;

FIGURE 55 is a view looking in the direction of the arrows 55—55 in FIGURE 53;

FIGURE 56 through FIGURE 65 are schematic wiring diagrams of electrical apparatus forming part of the invention;

FIGURE 66 is a plan view, partly in section, of a reset mechanism located within the housing;

FIGURE 67 is a sectional view taken on the line 67—67 of FIGURE 66;

FIGURE 68 is a sectional view taken on the line 68—68 of FIGURE 66;

FIGURE 69 is a sectional view taken on the line 69—69 of FIGURE 66;

FIGURE 70 is a view looking in the direction of the arrows 70—70 in FIGURE 66;

FIGURE 71 is a diagrammatic, elevational view of apparatus for resetting the pin fall registering devices and looking in the direction of the arrows 71—71 of FIGURE 66;

FIGURE 72 is a fragmentary, diagrammatic view of apparatus for resetting the strike-spare indicating mechanism and looking in the direction of the arrows 72—72 of FIGURE 66; and

FIGURES 73—81 are views illustrating scores of typical games.

In general, the apparatus comprises a score board having a plurality of parallel rows of openings therein, the number of openings in each row corresponding to the number of frames to be played in a game, and the number of rows corresponding to the number of players on two teams. Associated with each opening in the score board is a pin fall registering device which is adapted to record the score of each player, frame by frame. The pin fall registering devices are electrically connected to a series of switches located conveniently to the players so that the number of pins knocked down by each player in succession may be indicated by the manual setting of a selected switch. At some other location another switch is provided which must be operated by an opponent or neutral observer, after he agrees with the switch setting made by a player, in order to energize the electric circuit and cause actuation of the appropriate pin fall registering device.

Each pin fall registering device initially is obscured from view by a shutter. When all of the shutters are

closed, energization of the circuit causes all of the pin fall registering devices in a particular row to be actuated so that each pin fall registering device indicates the same score. When any shutter in a row is lifted, however, 5 mechanism is provided to disable further actuation of the visible pin fall registering devices in that row so that the visible devices will indicate the score attained in successive frames. All of the other, obscured registering devices in that row, however, are capable of further energization 10 so that each succeeding frame score may be recorded in a manner similar to that of the first frame. Associated with each indicating device of all of the rows of each team is mechanism for indicating the running total of the scores of all players on such team in a particular game and this total is always visible.

In the event a player bowls a spare or a strike, the score for that particular frame will not be determined until such time as the player bowls in one or more succeeding frames. Accordingly, mechanism is provided to 20 disable recording of a score in a frame where a strike or spare is rolled until such time as the score for that frame can be determined by the results of a succeeding frame or frames.

In team play is it customary for one team to bowl on one alley and then to move to an adjacent alley and bowl again. The scoring mechanism of the invention includes 25 shifting apparatus operable to shift the recording of a team's score from one alley to the other.

At the end of the game, the scoring apparatus must be 30 reset to condition it to record the scores of succeeding games and the apparatus includes such reset mechanism.

To facilitate understanding of the invention, each of 35 the major portions of the scoring apparatus will be described separately.

The control panel

The control panel is represented in FIGURES 1 and 2 by the reference character 1 and comprises a cabinet 2 mounted on a suitable support 3 which may be located 40 at the end of a ball return rack 4. The cabinet includes a front panel 5 having two sets of two parallel rows of levers L. There are eleven levers L in each row and associated with each lever is a symbol. With the top lever L at the extreme left hand side of the panel 5 is associated the strike symbol "X." This lever henceforth will be designated L_X. The adjacent lever L in the second row has associated with it the spare symbol "/". This lever henceforth will be designated L_/. The next nine levers in each tier are associated with the numerals 1 45 through 9 or the letter G, as the case may be, and the levers associated with the numerals henceforth will be designated by the letter L followed by the particular number with which it is associated, and the levers associated with the letter G will be designated L_G. One column of 50 levers L in each set is adapted to be used in conjunction with the rolling of a first ball in a frame whereas the second column of levers L is adapted to be used in conjunction with the rolling of a second ball in a particular frame. One set of levers is for use by the team members bowling 55 on the left alley and the other set is for use by the team members bowling on the right alley. Each lever has associated with it a multiple contact switch, as will be more fully explained in connection with the description of the electrical apparatus.

60 Each of the levers L is identical in construction, so it will not be necessary to show and describe each one in detail. Referring to FIGURES 3 and 4, each lever L comprises a disc 6 rotatably mounted on a spindle 7 which may be secured to the cabinet in any convenient manner 65 and to each disc 6 is connected a finger piece 8 which projects through an opening in the cover panel 5. The disc 6 also includes an ear 9 to which is connected one end of a spring 10, the other end of which is anchored to the panel 5. The spring normally urges the disc 6 to rotate in a clockwise direction, as viewed in FIGURE 4,

but clockwise rotation of the disc is limited by a stop member 11 adapted to engage the inner side of the panel 5.

Each disc 6 is provided with a notch 12 in its periphery which is adapted to be moved from the position shown at the left hand side of FIGURE 4 to the position shown at the right hand side of FIGURE 4, at which time a latch member 13 may drop into the notch 12 to maintain the lever L in the position to which it has been moved. By the time the latch 13 is in latching engagement with the lever L, the tab 9 will have moved to such position that it engages a contact member 14 of an electrical switch 15 for a purpose presently to be explained.

As is best shown in FIGURE 3, the latch 13 associated with each lever L is carried on a bar 16 which is mounted to rock on a pivot 17 secured to the inner side of the panel 5. Each bar 16 is urged by a spring 18 to rock in a direction to seat the latch 13 in its notch 12, and each bar 16 terminates in a rearwardly projecting arm 19. Below each arm 19 is a bar 20 which is carried by a vertically extending rod 21 located inwardly of the cabinet 1 and between the columns of levers L. The rod 21 is mounted for vertical movement in guides 22 and its lower end is connected to a spring 23 anchored to the base of the cabinet. The upper end of the rod 21 is connected to a slotted link 24 which, in turn, is connected to the plunger 25 of a scoring lever reset solenoid 26 that is fixed to the cabinet. The arrangement is such that upward movement of the rod 21 under the influence of the solenoid 26 will cause the bars 20 also to move upwardly and lift any latch 13 which may have been seated in a notch 12 out of the latter to permit the spring 10 to restore the lever L to its normal position.

As will become clear from the description to follow, the restoration of the levers L to their inactive positions normally is controlled automatically by the recording of a score. However, correcting means is provided to permit restoration of the levers L manually in the event any lever is in inadvertently depressed. The correcting means comprises a push button 27 (see FIGURE 5) mounted at the bottom of each set of levers L and which is adapted to bear against one arm of a bell crank 28 which is pivotally mounted in the cabinet on a pin 29. The other arm of the bell crank lever 28 is adapted to bear against a post 30 fixed to the vertical rod 21. The arrangement is such that depression of the push button 27 causes rocking of the bell crank lever 28 in a direction to elevate the rod 21 and cause the lifting of any latch 13 which may have been depressed, thereby permitting any inadvertently actuated lever L to be restored to its inactive position.

As is evident from FIGURE 2, each control panel comprises the two sets of vertical levers L. The left hand set of levers is for the purpose of recording the scores of the members of the team bowling on the left alley and the right hand set of levers is for the purpose of recording the scores of the members of the team bowling on the right alley. As will be pointed out more fully subsequently, the recording of scores for each team will be controlled by the levers associated with the alley on which a team member is bowling.

The scoreboard housing

The recording of the scores occurs in a housing 31, shown in FIGURE 6, as having a front wall 32, side walls 33, a top wall 34, a bottom wall 35, and a rear wall 36. The housing 31 is of a size and shape approximating the screens currently in use on many bowling alleys and is adapted to be suspended from the ceiling or supported in any other manner between a pair of adjacent bowling alleys. The front wall of the housing is equipped with a pair of vertically spaced holders 37 and 38 adapted to receive cards on which the names of two teams are printed. Below each card holder 37 and 38 is a plurality of holders 39 in which cards bearing team members' names may be inserted. In league play there usually are five members

to a team, so there should be at least five holders 39 associated with each team.

Aligned with each holder 39 is a row of windows or openings 40, the number of which corresponds to the number of frames, ten, to be played in a game. Above each opening 40 is a smaller window 41, but there are twelve such windows 41 in each row, instead of ten, for a purpose presently to be explained. Adjacent the right hand end of the front wall 32 is a pair of openings 42 and adjacent each opening 42 is the legend "Team Total." At the left hand side of the cabinet is a series of lights 43L, there being one light for each of the ten players. Similar lights 44R are associated with the team members and are located at the right hand edge of the housing. 15 These lights are adapted to be illuminated sequentially during play for the purpose of indicating which player of each team is bowling on the left or right alley.

On one or the other of the side panels 33 is mounted an off-on switch 45, a reset switch 46, and two pairs of 20 handicap switches 47 and 48. These elements will be described in more detail hereinafter.

Pin fall registering devices

Within the housing 31 and adjacent each of the windows 25 40 is a pin fall registering device 50 adapted to record the number of pins knocked down by a player, frame by frame. The devices 50 are best disclosed in FIGURES 7-17. Except for the devices opposite the first three windows in a row, all of the devices 50 are identical. 30 The difference between the three devices 50 at the left hand end of each row and the remainder will be pointed out as the description proceeds.

Each of the pin fall registering devices 50 comprises a plurality of number reels 51 on the periphery of each 35 of which is a series of numbers ranging from zero to nine, inclusive. Each of the reels 51 of all of the devices 50 is freely and rotatably mounted on a shaft 52 which runs the length of the housing 31 and is journaled at its ends in bearings 53 mounted on the side walls of the 40 housing. Each reel 51 is adapted to be actuated or indexed by means yet to be described so as to present to its associated window 40 numbers corresponding to a player's score. Since the maximum score that can be attained by a bowler in any of the first three frames will 45 have but two digits, only two reels 51 are required for the first three windows of each row of windows, but at each of the other windows 40 the devices 50 comprise three reels 51. This is the difference between the devices 50 adjacent the first three windows of a row and the remaining indicating devices. Hereinafter the reels will sometimes be referred to as units reels 51a, the tens reels 51b, and the hundreds reels 51c.

Adjacent each reel 51 is a disc 54 having ten equally spaced pins 55 arranged circularly and extending into 55 openings formed in its associated reel 51. The pins 55 constitute lugs interconnecting each disc 54 with its associated reel 51 and each lug associated with a units reel is adapted to be engaged by an adjacent pull bar 56 having its forward end shaped as a hook 57 capable of gripping 60 any one of the associated ten pins 55. The rear end of each pull bar 56 is pivoted as at 58 to a bar 59 that is fixed to a rock shaft 60 which runs the length of the housing 31 and is supported for rocking movement at its ends. Preferably, each rock shaft 60 is formed from 65 an angle iron, as is particularly indicated in FIGURE 11, connected at its ends to stub shafts 61 which are journaled in bearings 62 mounted on the end walls 33 of the housing 31. Parts like those just described with respect to the means for indexing the units reels are duplicated for indexing the tens reels and are identified by the same reference 70 characters, followed by the suffix a. No pull bars need be associated with the hundreds reels, or with the tens reels of those devices 50 having but two reels 51.

The arrangement is such that either the units reel 51 75 or the tens reel 51 of a particular device 50 may be

indexed entirely separately of one another, but there are certain conditions under which indexing of a units reel should cause indexing of the adjacent tens reel. Accordingly, keying means is provided on each of the units reels 51 for effecting indexing of its adjacent tens reel the space of one number when the units reel is indexed from nine to zero.

The keying apparatus is disclosed in FIGURES 15-17 and comprises a lever 63 rockably mounted on one of the pins 55 and having one of its ends formed as a hook 64. The other end of the lever 63 is connected to a spring 65 which is anchored on the disc 54. The arrangement is such that the lever 63 normally is held in such position that the hook 64 is located adjacent the periphery of the disc 54. However, a cam 66 is supported on the housing in a position to bear against the lever 63 and cam the hooked end radially inwardly. As is best shown in FIGURE 17, the hook 64 of the lever 63 extends laterally from the units disc 54 and the length of the hook is such as to permit it to engage any one of the pins 55 on the tens reel 51a. Thus, when the units reel is indexed from 9 to 0, the hook 64 will be actuated to engage a pin 55 on the tens reel and index the latter the space of one number. Keying mechanism identical to that just described is interposed between the tens reel and the hundreds reel in those registering devices having hundreds reels, but because it is the same as the apparatus just described, it is not necessary to describe it in detail.

Inasmuch as all of the numeral reels are freely rotatable on the shaft 52, means must be provided to prevent coasting of the reels and to assure stopping of the reels after indexing at positions where the numbers will be visible through the window openings 40. The anti-coasting means is disclosed in FIGURES 15 and 17 and comprises a bracket 69 clamped on the shaft 52 and carrying a pair of vertically extending guide rods 70 on which a carrier plate 71 is mounted for reciprocating movements. Between the plate 71 and the bracket 69 are springs 72 which urge the plate 71 to move upwardly. The plate 71 is provided with a pair of upstanding ears 73 between which is located a wheel 74 journaled on a shaft 75. The wheel 74 is adapted to engage two adjacent pins 55 and yieldably maintain the reel in fixed relation relative to the shaft 52. However, when the associated pull bar is actuated, a pin 55 will be capable of forcing the carrier plate 71 downwardly so as to permit the reel to be indexed. Each numeral reel is equipped with anti-coasting means of the character described, so it is unnecessary to illustrate more than one.

Operating means for the pin fall registering devices

The operating means for actuating the pin fall registering devices 50 is best illustrated in FIGURES 18-25, and comprises a number of horizontally arranged shift plates P located near the rear of the housing 31, there being one plate P for each row of pin fall registering devices. Each plate P is identical, so only one need be described in detail. As an aid to identification, the uppermost plate P will be referred to as plate P-1, the second highest plate P-2, and so on. Each plate P is mounted in slides 80 supported on the rear wall of the housing, the arrangement being such that each plate is capable of being shifted from side to side. At each end of a shift plate P is mounted a roller 81 and each plate has nine openings formed therein and numbered 82-90. Each plate also is provided with a pair of V-shaped notches 91 in which rollers 92 (see FIGURE 19) are located. The rollers 92 are mounted on pivoted arms 92a to which are connected springs 93 that urge the rollers toward one another. The arms 92a are pivoted to a support 94 that is secured to the rear wall 36 of the housing. The arrangement is such that the rollers 92 are at the apices of the notches 91 when a plate is in its neutral position, but when the plate is moved to one side or the

other of neutral position the rollers 92 exert a force on the plate via the springs 93 tending to urge the plate back to its neutral position.

At the left hand end of each plate P is a cam p and at the right hand end of each plate is a similar cam p'. The cams of the plate P-1 are identified by the reference characters p-1, p'-1; the cams for the plate P-2 are identified by the reference characters p-2; p'-2; and so on for each of the ten plates P. The cams p are adapted to close switches 21L, 22L, 23L, etc., when the appropriate plate P has been shifted to the left, and the cams p' are adapted to close switches 21R, 22R, 23R, etc., when the appropriate plate has been shifted to the right. Each of the switches is a multiple contact switch as will be brought out more fully hereinafter, and one of the contacts is adapted to illuminate the appropriate light 43L, 44R on the housing. This is perhaps better illustrated in FIGURE 56-1 wherein each of the lights 43L is adapted to be illuminated by the closing of the associated contact 21L, 22L, etc., and each of the lights 44R is adapted to be illuminated upon the closing of the associated contact LS21R, LS22R, etc.

As has been indicated, there are nine openings in each plate P, but for the present the description will be confined only to the openings 87 and 88.

Through the opening 88 extends a lever 95 (see FIGURE 11) which is riveted at one end to the rock bar 60. Through the opening 87 extends a lever 96 which similarly is connected at one end to the rock bar 60a. The openings 87 and 88 are of such size as to correspond substantially to the width of the levers which extend therethrough, but the openings 87 and 88 are considerably deeper than the thickness of the levers. The levers 95 and 96 extend to a point adjacent the rear wall of the housing 31.

Referring now to FIGURES 11 and 28, there is disclosed a plurality of vertically extending pull rods R. There are eighteen rods R arranged in nine pairs. Beginning at the left of FIGURE 28, the first pair of rods are numbered 100-L, 100-R, the second pair are numbered 101-L, 101-R, and so on to the extreme right hand pair of rods which are numbered 108-L, 108-R. The spacing of the rods of each pair from one another is substantially greater than the width of the pull bars 95 and 96, so that when the shift plates P are in their neutral position the bars 95 and 96 will be centered between their respective pairs of rods 106-L, 106-R and 105-L, 105-R. Each of the rods 106-L and 106-R is provided with a plurality of vertically spaced pairs of lugs 109-L and 109-R, respectively. Each of the rods 105-L, 105-R also is provided with a plurality of vertically spaced pairs of lugs 110-L and 110-R. The spacing between the individual lugs of each pair of lugs is such as to enable the associated pull bars 95 or 96 to be received therebetween when the associated shift plate P is moved either to the left or the right from its neutral position.

Referring now to FIGURE 10, the lower end of the pull bar 105-L is pivoted to a link 111 which, in turn, is pivoted to a lever 112 that is pivotally mounted on a bracket 113 secured to the inner surface of the front panel 60 of the cabinet. On the base of the cabinet, between the ends of the lever 112, is mounted a tens solenoid 114-L having its plunger 115 pivotally connected to the lever 112. The upper end of the pull bar 105-L is suspended from the upper panel of the cabinet by means of a spring (not shown). The arrangement is such that when the shift plate P-1, for example, has been shifted to the left from its neutral position, as is shown in FIGURES 11 and 18, the pull bar 96 will be received between the upper pair of lugs 110-L. In these positions of the parts, energization of the solenoid 114-L will cause the rod 105-L to be pulled downwardly, thereby effecting rocking of the rock bar 60a and, consequently, indexing of the tens reel 51b. Identical apparatus is provided for the pull bar 105-R and its operating solenoid is identified in the wiring diagram by the reference character 114-R. It will be

apparent that operation of the lever 96 and indexing of the tens reel 51a will be contingent upon the shifting of the plate P-1, however.

The construction and operation of the units reel pull bars 106-L and 106-R are the same as have been described with respect to the tens reel bars 105-L and 105-R. The solenoids for operating the units bars are designated 117-L and 117-R, respectively, in the wiring diagram.

Shift plate shifting apparatus

Reference has been made to the shifting of the shift plates P to the left and to the right of their neutral positions. The mechanism for shifting the shift plates is perhaps best illustrated in FIGURES 18, 22 and 23 and comprises a pair of vertical posts 118 and 119 located one at opposite ends of the shift plates P. Each post 118 and 119 is mounted for rotation in bearings 120 supported on the upper and lower walls of the cabinet housing and which are so located that the posts 118 and 119 are substantially in the same vertical plane as are the shift plates P. Projecting from the post 118 is a plurality of fingers 121. There are ten such fingers 121 and they are so arranged as to be spaced longitudinally of the bar 118 in accordance with the vertical spacing of the shift plates P. Each of the fingers 121 is angularly spaced from one another by 36° so that for each complete revolution of the post 118, each of the fingers 121 successively will be moved to a position in line with its associated shift plate P. Each of the fingers 121 is of such length that its movement to a position in line with its respective shift plate causes the associated finger 121 to bear against the roller 81 and displace the shift plate to the left, as is indicated by the position of the shift plate P-1 in FIGURE 18. When the post 118 has been rotated clockwise 36° from the position shown in FIGURE 18, the shift plate P-1 will be released by the finger 121 and the second finger 121 will have shifted the shift plate P-2 to the left. Further clockwise rotation of the post 118 releases the shift plate P-2 and shifts the shift plate P-3, and so on.

The post 119 is provided with fingers 122 similar in all respects to the fingers 121 and which function in a similar manner, but the arrangement of the fingers 122 is such that at the start of a game when the shift plate P-1 is shifted to the left by the associated finger 121, the shift plate P-6 will be shifted to the right by its associated finger 122, as is shown in FIGURE 18. The arrangement is such that rotation of the post 119 counterclockwise from the position shown in FIGURE 18 causes each of the shift plates P-6 through P-10 to be successively shifted towards the right and then causes each of the shift plates P-1 through P-5 to be successively shifted to the right.

Referring now to FIGURES 22-25, at the base of the cam shaft 118 is a ratchet wheel 123 which is keyed to the shaft 118. Rotatably mounted on the shaft 118 is a ratchet arm 124 on which is pivotally mounted a ratchet pawl 125. The ratchet arm 124 is connected to a link 126 which, in turn, is connected to the plunger 127 of a solenoid 128. The arrangement is such that energization of the solenoid 128 causes movement of the ratchet arm 124 through an arc of 36° so as to cause corresponding movement of the ratchet wheel 123 and of the shaft 118. When the arm 124 has traversed 36°, it engages a switch LS-219 which deenergizes the solenoid 128 in a manner presently to be explained so as to enable the ratchet mechanism to return to the position shown in FIGURE 25.

Also keyed to the shaft 118 is a toothed wheel 129 having ten notches 130 cut into its periphery. Each of the notches is adapted to receive a latch bar 131 which is mounted for reciprocating movements in a guide bracket 132. The bar 131 is adapted to be projected into a notch 130 by means of a spring 134 connected to the post, and the latter is adapted to be retracted

from the notches 130 by means of a solenoid 133. The arrangement is such that the shaft 118 may be indexed 36° for each operation of the ratchet mechanism. When the shaft has been turned 36°, the latch bar 131 is projected into one of the notches 130 so as securely to hold the shaft in its adjusted position. The notches 130 are, of course, so related to the fingers 121 that the locking of the shaft 118 occurs at those times when one of the fingers 121 is in a position to shift one of the shift plates.

Also mounted on the shaft 118 is a cam 135 (see FIGURE 27) which is so shaped as to close a switch LS-211 during one half the revolution of the shaft 118. The cam 135 is so arranged relatively to the shaft 118 that the switch LS-211 is closed only during the time that one of the players on team No. 2 is bowling on what shall be termed the left hand alley.

At the base of the cam shaft 119 are elements similar to those just described and which bear the same reference characters followed by the suffix a, with the exceptions that the switch corresponding to the switch LS-219 has been designated LS-236 and the switch corresponding to LS-211 has been designated LS-231. Contrary to the arrangement of the cam 135 and the switch LS-211, the arrangement of the cam 135a and the switch LS-231 is such that the latter is closed during those periods of time when a member of team No. 2 is bowling on what shall be termed the right hand alley. It thus will be apparent that whenever a member of team No. 2 is bowling on the right hand alley, the switch LS-231 is closed, and whenever a member of team No. 2 bowls on the left hand alley, the switch LS-211 will be closed. Since each switch can be closed only during half of the revolution of its companion shaft 118 or 119, it necessarily follows that if players of team No. 2 are bowling on both the left and the right hand alleys, both limit switches will be closed, and if players on team No. 1 are bowling on both alleys, both limit switches will be open. The switches LS-211 and LS-231 form part of a lock-out circuit which is designed to prevent the scores of players bowling on the left and right hand alleys being added at the same time if those men are on the same team. This circuit will be described in more detail subsequently.

Numerical reel shutters and disabling mechanism

The manner in which the units, tens and hundreds numeral reels 51 are actuated already has been described, and it will be recalled that all numeral reels are operated from the two rock bars 60 and 60a. At the beginning of a game the numeral reels will all have been set to indicate zero by means yet to be described and each window or opening 40 in the housing 31 will be covered by a shutter device S (see FIGURES 10-12). Each shutter device S is identical and comprises a plate 136 interposed between the numeral reels 51 and the windows 40, the plate being secured to arms 137 which extend rearwardly and are rotatably mounted by means of journals 138 on the shaft 52. Rearwardly of the journals 138 is a pair of arms 139 which are pivoted as at 140 to a pair of rearwardly extending bars 141 which, in turn, are pivoted as at 142 to a stationary support 143 which spans the length of the cabinet. Each of the two arms 141 is spanned by a roller bar 144 and each roller bar 144 is located adjacent and parallel to a cam shaft 145 which runs the length of the machine and is journaled at its ends in bearings 146 (see FIGURE 29) secured to the end walls of the housing. On the shaft 145 are fixed ten cams 147, there being one cam 147-1 located behind the first frame window 40, another cam 147-2 located behind the second frame window, and so on. As is best shown in FIGURE 30, each of the cams 147 has a dwell surface d and a lift surface l, the dwell surface d having a radius such that it is incapable of exerting a lifting force on the roller

bar 144. The lift surface l , however, is of greater radius than the dwell surface d so that when it is in engagement with the roller bar 144 it is capable of exerting a lifting force on the latter and cause rocking of the arms 139 and 137 about the axes of the journals 138 so as to cause the shutter plate 136 to drop, thereby exposing the numeral reels to view through the associated window 40. The cams 147 are so arranged as to cause each shutter 135 to be dropped from its numeral reel obscuring position successively as the scoring in each frame is completed.

As has been pointed out previously, the rock bars 60 and 60a span the length of the housing 31 and are connected to each of the pull bars 56, 56a so that rocking of the bar 60 will cause operation of all of the pull bars 56 and rocking of the bar 60a will cause operation of all of the pull bars 56a. It is necessary that all of the units and tens reels be actuated at the beginning of the game, but it is preferable that the operation of a particular pin fall registering device 50 be disabled after the score achieved in a particular frame has been recorded and the associated shutter opened. For this purpose, disabling means is provided which is effective to disable individual devices 50 from further operation when it has recorded the score in the frame just completed by a player.

Attached to the journals 138 is a pair of rearwardly projecting arms 148 which are spanned by a bar 149. When the shutter supporting arms 137 are rocked to drop the shutter 136, the bar 149 is raised to bear against the pull rods 56 and 56a so as to lift the latter to such positions that the hooks 57 and 57a are incapable of engaging the indexing pins 55. Consequently, opening of the shutter 136 disables the numeral reel indexing means for the particular frame opening 40 concerned.

The arrangement of the cams 147 is such that the shutters 136 are opened successively in a direction from left to right and beginning with the first frame opening 40. As each shutter is opened in succession, its associated pin fall registering device is disabled from further operation by the lifting of the pull bars 56 and 56a. The pull bars remain in their disabled position due to the cams 147 which are so formed and arranged on the cam shaft 145 that each successive cam has an increase in dwell area d over the preceding cam equivalent to approximately 32.7° , which is arrived at by dividing 360° by eleven, the number of increments of rotation of the cam shaft 145. The reason for rotating the shaft in eleven increments will be explained later. The cam shaft is rotated only when it is desired to advance the scoring of a game from one frame to the next and the means for rotating the shaft 145 forms part of the frame advancing means.

Frame advancing means

The frame advancing means includes a ratchet wheel 150 (see FIGURES 29-33) fixed on the cam shaft 145 and having eleven teeth uniformly spaced around its periphery. Pivoted on the housing as at 151 is a ratchet arm 152 to which is pivotally connected a ratchet pawl 153 that is adapted to engage the teeth of the ratchet wheel 150. The pawl 153 is adapted to be restored to its initial or operative position by means of a spring 154. Pivotally connected as at 155 to the ratchet arm 152 is a rearwardly extending bar 156 which extends through the opening 86 (FIGURE 18) in the shift plate P-1 and is received between the vertical operating bars 104-L and 104-R. These bars are provided with a plurality of pairs of lugs 157-L and 157-R, similar to the lugs 110-L and 110-R, and between which the bar 156 may be trapped when the shift plate P-1 is shifted in one direction or the other. Each rod 104-L and 104-R is adapted to be actuated by a linkage similar to the linkage 111-113, but which is not shown, so as to avoid undue multiplication of figures. Each operating bar 104-L and 104-R also has associated with it a solenoid 160-L and 160-R, respec-

tively, which are shown only in the wiring diagram. The arrangement is such that energization of either of the solenoids 160-L and 160-R when the shift plate has been moved to the left or to the right, respectively, will cause rocking of the ratchet arm 152 so as to effect indexing of the shaft 145 and, consequently, opening of one of the frame windows and conditioning of the cams 147 for opening of the next succeeding frame window.

In order to prevent coasting of the shaft 145 and its cams 147, the shaft has fixed thereto a toothed wheel 161 (FIGURE 33) adapted to be engaged by a roller 162 which is mounted at the end of an arm 163 pivoted as at 164 to rock against the force of a spring 165 which is anchored as at 166 to the housing.

If the scoring of a bowling game consisted merely in the summation of pins knocked down in a particular frame, it would be a relatively simple matter to provide a mechanical scoring apparatus. As is well known, however, a player bowling a spare or strike adds to the number of pins felled in that particular frame the number of pins knocked down on the throwing of the first or second ball, as the case may be, in the next succeeding frame or frames. This being the case, means must be provided for recording strikes and spares. However, it is customary for the strike or spare to be recorded in the frame in which it was scored. Means is provided in the apparatus constructed in accordance with the invention for recording the scoring of a strike or spare.

Strike and spare recording means

It has been pointed out earlier that the front panel 32 of the cabinet is provided with a plurality of windows or openings 41 in each player row for indicating when a strike or spare is scored. Although there are only ten frames in a bowling game, a player who scores a strike in the tenth frame is entitled to roll two additional balls and it is possible that he may score two additional strikes, each of which should be recorded. Accordingly, there are twelve windows 41 for each player row, rather than ten.

The strike-spare indicating mechanism is perhaps best illustrated in FIGURES 34-36 and comprises for each opening 41 an indicator slide member 170 mounted just inside the front panel 32 in rails 171 and guides 172 for sliding movements to and fro relative to its associated window 41. Each of the members 170 is in the form of a plate 173 having a length substantially greater than the width of the opening 41. Each plate 173 initially is held against a pair of stops 174 by means of a spring 175 which is connected to one end to the plate 173 and anchored at its other end to a lug 175a projecting rearwardly from the inner surface of the front panel 32. The stops 174 also project rearwardly from the front panel. When a plate 173 is in its initial position, a blank surface is presented to the opening 41 or, stated differently, nothing is indicated initially by the member 170. However, each plate 173 carries both a spare symbol / and a strike symbol X.

Thus, should the member 170 be moved from its initial position, it will indicate selectively a spare or a strike. Spare and strike symbols conventionally are referred to as "marks."

Means is provided for effecting movement of the strike-spare indicating members 170 when a strike or spare has been scored and comprises what will be referred to as a mark bar 176 (see FIGURE 36). The mark bar comprises a shaft 177 which extends longitudinally of the cabinet 31 adjacent the line of plates 173. One end of the shaft 177 is rotatably received in a carriage 178 and the other end of the shaft 177 is rotatably received in a similar carriage 179. The carriage 178 is provided with ears 181 which slidably receive guide rods 180 which are supported adjacent one end wall of the cabinet (see FIGURE 7) and the carriage 179 is similarly mounted on guide rods 182 by means of ears 183. The shaft 177 is movable with the carriages 178 and 179 for a purpose later to be explained. The guide rods 182 are supported on plates 184 (FIGURE 9) which are secured to a

bracket 185 that is secured to the opposite end of the cabinet housing wall. Uniformly spaced along the length of the shaft 177 are twelve radially projecting fingers 186, there being one finger for each of the twelve indicator members 170. The fingers 186 not only are spaced longitudinally of the shaft, but are angularly spaced from one another by 30°. The angular disposition of the fingers 186 is for the purpose of permitting each of them successively to be moved to a position in which it projects directly towards its associated indicator plate 173. This will require rotation of the shaft 177 in successive increments of 30°, but for the moment let it be assumed that the shaft is in such position that only the finger 186 which is adjacent the carriage 178 projects towards the indicator member 170 associated with the first frame opening 41. In these positions of the parts, the first finger 186 will, as is best shown in FIGURES 7, 34 and 35, be adjacent a tab 187 which extends rearwardly from the plate 173. Each plate 173 is formed with a similar tab. Because of the angular relation of the several fingers 186, only one of the twelve fingers will be in a position to engage a tab 187 at any given time.

Means is provided to rotate or index the mark bar in accordance with the operation of the frame advance mechanism previously described so as to condition the mark bar to record a strike or a spare in the frame it is scored. The mark bar indexing mechanism is best shown in FIGURES 36 and 38 and comprises a ratchet wheel 188 secured to the shaft 177 within the carriage 178 and having twelve teeth spaced 30° apart from one another. A ratchet arm 189 is pivoted as at 190 for rocking movements and is connected at one end to a ratchet pawl 191 which is adapted to engage the ratchet teeth and index the shaft 177 upon rocking of the arm 189. The pawl 191 is biased by a spring 192 towards the teeth of the ratchet wheel. At the other end of the ratchet arm 189 is pivoted a bar 193 which extends through the opening 85 in the shift plate P-1 and is received between the pair of operating bars 193-L and 193-R (FIGURE 28). The operating bars 193-L and 193-R are equipped with lugs 194-L and 194-R, respectively, which function in a manner similar to the lugs previously described and the operating bars 193-L and 193-R are mounted in a manner similar to those previously described and are respectively actuated by solenoids 195-L and 195-R, which are shown only in the schematic wiring diagram. The arrangement is such that the bar 193 will be received between a pair of lugs 194-L or 194-R upon operation of the shift plate P-1, as hereinbefore described, so that energization of the solenoid 195-L and 195-R will cause rocking of the bar 193 and actuation of the ratchet mechanism to index 30° the shaft 177.

Also mounted on the shaft 177 within the carriage 178 is a toothed wheel 196 (see FIGURE 39) which operates in conjunction with a spring biased latch device 197 to prevent coasting of the shaft 177 in a manner similar to that described earlier in connection with the cam shaft 145.

From the foregoing it will be understood that the mark bar 176 is advanced or rotated 30° frame by frame so as to be in condition to indicate the scoring of a strike or spare. In the event a strike or spare is scored, the player will throw the appropriate switch L-/ or L-X so as to condition the apparatus for recording the spare or strike.

The mechanism for recording a spare is disclosed in FIGURES 9, 34, 36, and 40, and comprises a crank arm or plate 198 pivotally mounted on the bracket 185 by means of a pivot pin 199. One end of the crank 198 is pivotally connected to a lost motion link 200 which receives a post 201 projecting upwardly from the carriage 179. At the other end of the crank 198 is pivoted a similar link 202 which also is pivoted to one end of a lever 203 (FIGURE 40), the other end of which is pivoted as at 204 to a support 205 fixed on the cabinet. Adjacent the lower end of the lever 203 is pivoted a rearwardly project-

ing bar 206 which projects through the opening 90 in the shift plate P-1 and is received between the pair of operating bars 198-L and 198-R. These operating bars are provided with operating lugs 207-L and 207-R, are mounted for movement in a manner similar to the previously described operating bars, and are respectively actuated by solenoids /L and /R shown in the wiring diagram. The arrangement is such that operation of either solenoid when the shift bar P-1 has been shifted to one or the other of its positions will effect rocking of the lever 198 about the pivot 199 in a direction to cause the carriage 179 to be pulled in a direction longitudinally of the shaft 177. Since the shaft 177 is mounted to move with the carriage 179, the shaft and each of the fingers 186 also will be moved under the influence of the lever 198. Whichever finger happens to be in a position to engage the tab 187 on the associated recorder plate 173 will cause that plate to be shifted against the force of its spring 175 in the same direction that the shaft 177 is pulled. The arrangement is such that operation of the lever 198 will effect movement of the shaft 177 only a distance sufficient to move a plate 173 enough to expose the spare symbol.

The strike recording mechanism is quite similar to the spare recording mechanism and comprises a lever 208 pivoted as at 209 to the bracket 185 and being pivoted at one of its ends to a lost motion link 210 which receives a stud 211 projecting upwardly from the carriage 179. The other end of the lever 208 is pivoted to a link 212 which in turn is pivoted to a lever 213 that is similar to the lever 203. To the lever 213 is pivoted a rearwardly projecting rod 214. The rod 214 extends through the opening 89 in the shift plate P-1 and is received between the pair of operating rods 107-L and 107-R, the latter being provided with operating lugs 215-L and 215-R, respectively, and being mounted in a manner similar to the operating bars previously disclosed, but being operated by solenoids X_L and X_R, shown only in the wiring diagram. When a strike is to be scored, the appropriate solenoid X_L or X_R is actuated so as to cause rocking of the lever 208 about its pivot 209.

As is best shown in FIGURE 36, the distance between the pivot 209 and the connection of the lever 208 to the link 212 is half the distance of the corresponding elements of the spare indicating mechanism. Accordingly, rocking movement of the lever 208 under the influence of the part 214 will be twice the rocking movement imparted to the lever 198 by the part 206 and will effect, consequently, twice the movement of the carriage 179, the shaft 177, and the fingers 186. Movement of the shaft 177 under the influence of the strike indicating mechanism, therefore, will cause twice the movement of the indicator plate 173 engaged by one of the fingers 186 so as to move the latter relatively to the window 41 a distance sufficient to enable the strike symbol X to be visible through the window.

It will be recalled that each indicator plate 173 has connected to it a spring 175 which yieldably holds the plate in its initial position. Because of the spring, it is necessary that means be provided to hold the indicator plate in its spare or strike indicating position after it has been moved by the mark bar apparatus. Accordingly, a latch member 220 (see FIGURE 34) is pivoted as at 221 on the housing wall 32 above each indicator plate 173 and is equipped with an arm 222 which is adapted to drop into a recess 223 to hold the plate 173 in its spare indicating position or to drop into a notch 224 to hold the plate in its strike indicating position. The latch 220 is urged towards its latched position by means of a spring 225 having one end connected to the latch and the other end connected to a post 226 secured to a downwardly extending projection 227 forming part of a reciprocable upset bar 228 which is mounted for sliding movements in guides 229 that are secured to the inner surface of the front panel member 32. The operation of the upset bar 228 will be described hereinafter.

In those instances where a spare or strike is scored, it is necessary that the pin fall registering device for that particular frame be capable of indicating the number of pins felled by the next one or two balls. Accordingly, the shutter for any particular frame, including the tenth, must not be opened in a frame where a spare or strike is thrown. Means is provided for delaying the disabling of the pin fall registering device in a frame where a strike or spare is scored and may best be referred to as a memory device. Another matter which will be treated more in detail hereinafter is the mechanism by means of which the circuit to a particular player's line or row is maintained open in the event that player rolls a spare or strike in the tenth frame. For the present, however, it will suffice to say that the mark bar shaft 177 has an arm 230 (FIGURE 41) fixed thereto and arranged to correspond exactly to the angular position of the finger 186 which is opposite the eleventh window 41, and a similar arm 231 (FIGURE 42) which is arranged to correspond exactly to the angular position of the finger 186 opposite the twelfth window 41. Each of the fingers 230 and 231 is located within the carriage 179. Adjacent the arm 230 is a switch LS-11 and adjacent the arm 231 is a switch LS-12, the arms being adapted to actuate the switches when the mark bar has been rotated to condition operation of the eleventh and twelfth indicator plates 173.

The memory apparatus

The memory apparatus is best disclosed in FIGURES 44-48 and comprises four units, namely, a spare memory unit 235, a strike memory unit 236, a back-off unit 237 for operation during the game and a control unit 238.

On the rear wall 36 of the cabinet 31 is mounted a base member 239a supported by a pair of spaced apart angle bars 239 between which extends a shaft 240 journaled at its ends for rotation in bearing supports 241. Adjacent the left hand end of the shaft 240, as viewed in FIGURE 44, is keyed a cam disk 242 having a single lobe or tooth 243 forming part of the spare memory unit 235. Mounted on an arm 244 is a U-shaped guide sleeve 245 in which is slideably received a ratchet pawl 246 which is adapted to be moved upwardly into engagement with the tooth 243. A pin 247 on the pawl prevents its dropping through the sleeve 245. The pawl 246 is pivoted as at 248 to a lever 249 which is pivotally mounted on a shaft 250 which is supported by bearing supports 250a carried by the member 239. To the other end of the lever 249 is pivoted an arm 251 which extends through the opening 82 in the shift plate P-1 and is received between the pair of operating levers 100-L and 100-R. These rods, like those previously described, are provided with pairs of operating lugs 252-L and 252-R which function, when the shift plate P-1 has been moved either to the left or to the right of its neutral position, to effect rocking of the lever 249 in a direction to cause rotation of the cam 242 and the shaft 240 in a clockwise direction as is viewed in FIGURE 45. The operating bars 100-L and 100-R are actuated through linkages similar to those previously described, and in response to the energization of solenoids MS/L and MS/R shown only in the wiring diagram.

Adjacent the cam 242 is a cam 253 which is similar to the cam 242, but is provided with two teeth 254. A ratchet mechanism 255, generally similar to the ratchet mechanism described in conjunction with the spare memory unit 235, is included in the strike memory unit 236 and is adapted to be operated by rocking of a lever 256 which is journaled on the shaft 250. To the lever 256 is pivoted an arm 257 which passes through the opening 83 in the shift plate P-1 and is received between the two operating rods 101-L and 101-R which, like the others previously described, are provided with pairs of operating lugs 258-L and 258-R. The operating rods 101-L and 101-R are operated through linkages similar to those previously described in response to energization of sole-

noids MSX-L and MSX-R, shown only in the wiring diagram. The stroke length of the lever 257 is twice the length of the stroke of the arm 251, however, so that the operating pawl of the mechanism 255 will advance the shaft 240 twice as far as the mechanism 235, for a reason to be explained hereinafter.

As has been pointed out, the cam 253 is provided with two teeth 254. The reason for the two teeth is to enable the shaft 240 to be indexed clockwise twice in the event a player scores two strikes in succession. The significance of this construction will become apparent subsequently.

The back-off unit 237 comprises a cam 259 keyed to the shaft 240 and provided with three lobes or teeth 260. In contrast to the location of the teeth or lobes 243 and 254 previously described, the lobes 260 are located on the opposite side of the cam 259. Mounted on the base 239a is a support 261 through which slideably extends a ratchet pawl 262, the pawl having a pin 263 thereon which causes the pawl to occupy a position free of the teeth 260 during periods of inactivity of the mechanism 237. The pawl is pivotally connected to one end of a lever 264 which is rockably mounted on the shaft 250. Between the pawl 262 and the lever 264 is a spring 265 which urges the pawl in a direction such that one of its ends is enabled to engage the teeth 260. At the other end of the lever 264 is pivoted an arm 266 which extends through the opening 84 in the shift plate P-1 and is received between the pairs of operating rods 102-L and 102-R. These operating bars, like the others, are equipped with pairs of operating lugs 267-L and 267-R. Like the other operating rods, the rods 102-L and 102-R are connected to links in such manner as to enable them to be vertically reciprocated under the influence of solenoids MSZ-L and MSZ-R shown only in the wiring diagram.

As will be apparent from FIGURE 47, operation of the indexing pawl 262 will, upon engagement of the pawl with a tooth 260, effect rotation of the shaft 240 in a counterclockwise direction. That is, operation of the unit 237 causes movement of the shaft 240 in a direction opposite to the operation of either of the units 235 or 236.

In each of FIGURES 45-47, the shaft 240 and the cams 242, 253, and 259 are in the positions they would assume prior to the beginning of a game. Thus, operation of the indexing mechanism for the unit 235 would cause indexing of the cam 242 and the shaft 240 clockwise by about 30°. Operation of the indexing apparatus 255 of the unit 236 once would cause a similar rotation of about 60° of the shaft 240 in a clockwise direction. When the shaft 240 is in the position shown in FIGURE 47, operation of the mechanism 237 has no effect inasmuch as the teeth 260 are out of the path of movement of the pawl 262. If the spare mechanism 235 has been actuated once, however, the shaft 240 will have been advanced 30°, whereas if the strike unit 236 has been actuated once, the shaft 240 will have been advanced 60°. Under these conditions, one actuation of the back-off unit will return the shaft 240 30°. Thus, if the mechanism 237 is operated after actuation of the spare mechanism 235, the shaft 240 will be restored to the position shown in FIGURES 45-47, but if the mechanism 237 is operated after actuation of the strike mechanism 236, the shaft 240 will be returned only 30° of the 60° it had been advanced.

The operating characteristics of the devices 235, 236, and 237 will be referred to in more detail hereinafter.

The unit 238 disclosed in FIGURE 48 comprises a cam 268 which is keyed to the shaft 240 so as to rotate with the latter. The cam 268 has a single lobe 269 which is adapted to make contact with and close any one of three switches, LS/, LSX, and LSXX, which are mounted in the path of movement of the lobe 269 on a support 270. The opposite side of the cam 268 is provided with

three notches 271 and a fourth notch 272 which are adapted to cooperate with a wheel 273 mounted at the end of an arm 274 pivoted on a support 275 and urged by spring 276 into engagement with the cam 268 so as yieldably to hold the shaft 240 in whatever position it may be moved by the units 235, 236, or 237.

The cam 268 also includes a laterally projecting pin 278 which is received in a slot 279 formed at one end of an arm 280, the other end of which is pivoted as at 281 to an arm 282 of a bell crank lever 283 pivotally mounted as at 284 on a support 285 secured to the rear wall of the cabinet. The other arm 286 of the bell crank lever is connected by a spring 287 to a lug 288 which projects from a vertically movable link 289 and about which more will be said hereinafter.

The arrangement of the cam 268 is such that when the shaft 240 has been indexed clockwise 30° by the spare memory unit 235, the lobe 269 will engage and close the switch LS/. When the cam has been indexed 60° by operation of the strike unit 236, the lobe 269 will engage and close the switch LSX. Upon indexing of the cam 268 an additional 30°, the lobe 269 will engage and close the switch LSXX. The significance of this characteristic of the unit 238 will be described later.

Although only one each of the units 235, 236, 237 and 238 has been illustrated, it will be understood that these units are duplicated for each player's line and are operable by the left- or right-hand rotors and related electrical mechanism yet to be described.

Team total devices

It has been pointed out earlier that the front wall 32 of the cabinet 31 is provided with a pair of openings 42 through which the total score attained by each of the two teams may be seen. A team total device is shown in FIGURES 49-51 and comprises a shaft 300 journaled for rotation at its ends in bearings 301, one of which is secured to the adjacent end wall of the cabinet 31 and the other of which is mounted on a support 302 fixed to the inner side of the cabinet front wall. Rotatably journaled on the shaft 300 is a plurality of numeral reels 303 which are identical in all respects to the numeral reels 51 previously described. In the disclosed embodiment, there is one reel to indicate units, another reel to indicate tens, and another reel to indicate hundreds. Normally, three reels are sufficient to indicate the total score of a team of five members, but more reels may be used if desired. Associated with each of the units and tens reels is a hooked pull bar 304 and 305, respectively, which operate like the pull bars 56 and 56a to index the associated reels 303. Although not shown, a coupling device like those previously described in connection with the pin fall registering devices may be associated between each of the reels so that upon a complete revolution of the units and tens reels, the tens and hundreds reels, respectively, will be indexed $\frac{1}{10}$ revolution. To the pull rod 304 is connected the plunger 306 of a solenoid 307 and to the pull rod 305 is connected the plunger 308 of a solenoid 309. Upon energization of the solenoid 307, the units numeral reel 303 will be indexed numeral by numeral and upon energization of the solenoid 309, the tens reel 303 will be indexed numeral by numeral.

It is preferable that the numeral reels 303 be visible at all times. Consequently, there is no necessity for providing shutters for the team totals units. However, it is necessary that the pull bars 304 and 305 be disabled during the resetting of the numeral reels 303 to their zero positions. Disabling of the rods 304 and 305 is accomplished by means of a plate or tab 314 fixed to a rotatable shaft 315 which is journaled at its ends in bearings 316 for rocking movement from a normal, generally horizontal position of the tab 314 to an elevated position of the tab so as to bear against and lift the arms 304 and 305 to enable the numeral reels 303 to be returned to their zero positions. This mechanism will be explained in more detail subsequently.

Only the team total indicator for the No. 1 team has been shown in FIGURES 49-51, but it should be understood that a duplicate arrangement is provided for the No. 2 team total mechanism.

Operating rotors

Within the control panel 1 are located two rotors, one behind the left hand row of levers L used in conjunction with recording scores of the players bowling on the left hand alley and the second rotor being located behind the right hand row of levers L for recording the scores of the player bowling on the right hand alley. Each rotor is identical and only one will be shown and described in detail.

15 A rotor is best disclosed in FIGURES 52 and 53, and comprises a disk 326 having its center coaxial with a rotatable shaft 327, but the disk 326 does not rotate with the shaft 327. Spaced around the periphery of the disk 326 are forty-four electrically conductive contact numbers numbered 328 through 371. Each of these contacts is connected by wires shown in the wiring diagram to various electrically operable parts.

20 Fixed on the shaft 327 is an arm 372 (see FIGURES 53 and 54) and at one end of the arm is mounted an electrically conductive brush 373 which rotates with the arm 372 and is adapted to contact each of the forty-four contacts 328-371 successively. The opposite end of the arm 372 is provided with a part 374 which is adapted to engage and close a switch LS-54 when the traveling brush 373 passes the last contact 371. The switch LS-54 has overlapping contacts LS-54L-1, and LS-54L-2 (shown only in the wiring diagram) the former being normally open and the latter being normally closed, but being held in their actuated positions by the part 374 when the rotor is at rest.

25 Adjacent one end of the shaft 327 is mounted a commutator ring 375 which is electrically connected to the traveling brush 373 through a wire 376. In engagement with the ring 375 is a brush 377 supported on a fixed arm 378, the brush 377 being connected by a wire 379 to a power source.

30 At the other end of the shaft 327 is a gear 380 which meshes with a gear 381 mounted on the shaft of a gear reduction unit 382 that is driven by an electric motor 383. Preferably, the reduction unit 382 is such as to reduce 35 the speed of rotation of the traveling brush 373 to about five or ten revolutions per minute.

35 Yet to be described are the wiring diagrams and the machine resetting mechanism, as well as the operation of the machine, but it is believed that a better understanding 40 of the invention may be obtained if a general description of the scoring operation of the machine is described at this time since such description will cover a great deal of the wiring diagram. The reset mechanism will be described afterwards.

General scoring operation

45 When the machine is conditioned for operation at the beginning of a game, all of the numeral reels of the pin fall registering devices 50 will be set at zero, all of the shutters will be closed so as to obscure each of the numeral reels of the pin fall registering devices, and all of the strike-spare indicating plates 173 will be in their initial or non-indicating positions. In addition, the numeral reels 303 of the team total devices also will be 50 in their zero positions unless one team is to be awarded a handicap. If a handicap is to be given, the appropriate indexing solenoids 307 and 309 may be actuated manually by operation of the handicap switches 47 and 48 mounted on the cabinet. Prior to the beginning of a 55 game, the shift plates P-1 and P-6 will be displaced from their neutral positions by their associated fingers mounted on the cam shafts 118 and 119. For the sake of illustration, it will be assumed that the first player on team No. 1 will begin the same on the left hand alley and 60 the first player on team No. 2 will begin the game

on the right hand alley. The positions of the shift plates P-1 and P-6 therefore will conform to the arrangement shown in FIGURE 18. Each of the traveling brushes of the apparatus at this time also will be in its initial position. That is, the left hand brush 373 will be located between the contacts 328 and 371 and its switch LS-54 will be engaged by the arm 374. An arrangement will be similar for the mechanism associated with the right hand rotor.

In FIGURES 56-1 and 56 there are shown two power lines, X and N, leading to a source (not shown) of alternating current. For the present it will be assumed that the No. 1 player of the first team is to bowl on the left hand alley. Shift plate P-1, therefore, will have been shifted to the position shown in FIGURE 18 so as to close the switch 21L and to move to the left all of the levers that extend through the openings 82-90 in the shift plate P-1. Such levers therefore will be so related with the lugs on their respective pull rods as to enable the recording of a score to be performed. Moreover, the closing of the switch 21-L will have closed its associated contact LS-21-1 (FIGURE 56-1) to illuminate the associated light 43-L-1. Closing of the switch 21-L also will close the associated contact LS-21L-2 (FIGURE 56). Before the first ball is rolled, it will be apparent from FIGURE 56 that each of the circuits through the first ball and second ball levers L is open, since none of them has been moved. The contact LS-54L-1 of the switch LS-54, however, will be closed, due to its engagement by the part 374. The switch LS-54L-2 is open, however, so the driving motor 383 is incapable of operating even though the contact LS-21L-2 is closed.

Interposed in the line connecting the first and second ball switches L and the second bank of permissive switches, is a starting relay Rs having a pair of normally open contacts Rs-1 and Rs-2. Bridging the contact Rs-1 is a normally open, manually operable, switch 385 which must be operated by someone other than the team player in order to have the player's score registered. The switch 385 henceforth will be referred to as the confirm switch and it has a normally closed contact 385c which is mounted in the line containing the normally open contact Rs-2.

A typical game is illustrated in FIGURE 73. The scoring of each frame will be described in detail. Assume that the first player on team No. 1 rolls his first ball and knocks down six pins. He then will depress or actuate the lever L-6-1 in the first ball row of levers. Actuation of the lever L-6-1 will not, however, have any effect on the apparatus at this point because the first ball levers L are isolated from the power source by normally open contacts R11-L and R12-L of relays R11 and R12. These relays are, as later will be more fully explained, adapted to be operated to connect the first ball levers L to the power source only when a player is bowling in the eleventh or twelfth frame. In other words, in a normal, ten-frame game, actuation of the first ball levers has nothing to do with the operation of the scoring apparatus and might well be dispensed with. Inasmuch as a player may score either a strike or a spare in the tenth frame, however, some means must be provided to record the score attained by the player when he rolls either two or one additional ball and it is for this purpose that the first ball levers are included.

Now assume that the first player knocks down three more pins when the second ball is rolled. The total number of pins felled by the player in the first frame then is nine, so the lever L-9-2 opposite the number 9 in the column of second ball levers is actuated or depressed. The closing of the second ball switch L-9-2 will condition the starting relay RS for energization upon the closing of the confirm switch 385. When the switch 385 is closed, the relay RS is energized, thereby closing the contacts RS-1 and RS-2. At this point it should be pointed out that confirm switch contact 385c opens upon

5

the closing of the switch 385, but closes when the switch 385 reopens. The reason for this is to prevent someone from holding the confirm switch 385 closed so as to cause the motor 383 to continue to operate and add the score several times.

Upon the release of the confirm switch 385, and the closing of its contact 385c, a circuit will be completed through the contact RS-2, the contact 385c, and through a normally closed contact r of a lockout relay R to the motor 383, and from the motor to the power line N through the permissive limit switch contact LS-21-L which is held closed by the cam p-1 on the shift plate P-1. As is shown in FIGURE 56, the switches LS-211 and LS-231 are arranged to complete a circuit through a conductor a to a lockout relay R which can only be energized when the two switches LS-211 and LS-231 are in either their inactive positions or in their activated positions with relation to a conductor b that parallel the conductor a. As has been pointed out earlier, the switch LS-231 is controlled by the cam 135a on the cam shaft 119 and the switch LS-211 is controlled by the cam 135 on the cam shaft 118. A circuit to the lock out relay R is completed through the conductor a when any one of the shift plates P-1-P-5 has been shifted to the left, as in FIGURE 18, and when another one of the shift plates P-1-P-5 has been shifted to the right. A circuit is completed to the relay R through the conductor b when any one of the shift plates P-6-P-10 has been shifted to the right and when another one of the shift plates P-6-P-10 has been shifted to the left. Thus, in the case where players No. 1 and No. 5 on team No. 1, for example, are bowling simultaneously on different alleys, the switches LS-211 and LS-231 will be so positioned as to prevent the completion of a circuit to the relay R. Consequently, the relay R will be de-energized and the normally closed contact r will be opened so as to prevent simultaneous recording of the scores of both players on the same team total device.

Even with the contact r open, a circuit can be completed to the motor 383, after energization of the starting relay Rs, through a closed contact LS54-R of a switch similar to the switch LS54, but associated with the right hand rotor. The contact LS54-R will be closed as long as the right hand rotor is in its initial position corresponding to the initial position of the rotor 326. Whichever player completes his frame first and initiates the scoring mechanism will have his score recorded, and the other player must wait until such scoring is completed before his scoring can be begun. When the recording of the first player's score is completed, the recording operation for the second player's score will begin automatically. This arrangement prevents the recording of more than one player's score on the same team at any one time which would cause inaccurate recording of the team's total.

Starting of the motor 383 will cause the traveling brush 373 to begin a cycle of operation. Shortly after the traveling brush 373 begins to move, the switch LS54 is disengaged by the arm 374 and the switch LS54-L-1 opens. Consequently, the traveling brush can make but a single revolution. The contact LS54-L-1 is not opened, however, until such time as the normally open contact LS54-L-2 has closed. As a result, the relay Rs is de-energized and power is supplied to the motor 383 until such time as the contact LS54-L-2 again is opened by the arm 374, thereby completing one complete revolution of the brush.

Referring now to FIGURE 57, rotation of the traveling brush 373 will cause it first to engage the contact 328 on the disk 326. The contact 328 is connected to the solenoids SXL and S/L which are adapted to actuate the strike and spare recording means, respectively, but since neither the strike or the spare levers have been thrown, the solenoids SXL and S/L are isolated from the circuit. Each of the next nine contacts engaged by the traveling brush is associated with the column of first ball levers L

and, as has been indicated, these levers are isolated from the circuit unless one of the relays RXXL or R/L is energized by its memory device, it being understood, of course, that the first frame can not be preceded by either a strike or a spare. Consequently, the brush passes over these contacts without any action taking place.

Each of the contacts 338, 340 and 342 is associated with the strike lever LX and, since that lever has not been thrown, the brush travels past these contacts with no action taking place. The contacts 339 and 341 are associated with the spare and strike memory devices, respectively, and since neither a spare nor a strike has been scored up to this point, the brush passes over these contacts with no action taking place.

Referring now to FIGURE 58, the next contact engaged by the brush 373 is contact No. 343. This contact is connected to the strike-spare recorder advance solenoid 195-L which is energized at this point so as to cause downward movement of the operating bar 103L with resultant rocking of the arm 193 and indexing of the shaft 177 so as to remove the finger opposite the first window 41 to a position in which it is incapable of engaging the tab 187 on the first frame strike-spare indicating plate 173. Indexing of the shaft 177 will locate the second finger 186 in a position to engage the tab 187 of the second plate 173, should a strike or spare be scored in the second frame bowled by the first player.

The next nine contacts engaged by the traveling brush are the contacts 1b through 9b which are associated with the second ball column of levers L. Each of these contacts, however, is associated with the strike memory device and, since no strike or double strike precedes this frame, the brush travels over the contacts without any action taking place.

The next contact in the path of the brush is contact No. 353. This contact is associated with the spare recording mechanism and, since no spare was scored in frame No. 1, nothing takes place upon its engagement by the brush. Similarly, nothing takes place upon engagement of the contact 355 with the brush inasmuch as a spare was scored in the first frame.

The next nine contacts, 356-364 (see FIGURE 59) are associated with switches 1b through 9b which also are associated with the second ball column of levers L. It will be recalled that the lever L-9-2 was actuated, since nine pins were felled by both balls in the first frame and, thus, the switch 9b will be closed. As a result, a circuit will be completed from the contact 364 to a line leading to a relay RU (shown in FIGURE 57). As is shown in FIGURE 59, each of the switches 1b-8b is connected with its associated rotor contact and is arranged to provide a circuit from each contact 356-365 to the units relay. Thus, as the brush engages each of the contacts 356-364, nine successive impulses will be transmitted to the relay RU. As each impulse is transmitted to the relay RU, a contact Ru-1 of that relay will be closed instantaneously so as to cause the units solenoid 117-L to pull the operating bar 106-L downwardly, thereby rocking the rock bar 60 and effecting nine successive increments of motion to all of the units numeral reels 51, because at this stage of the game each of the pull bars 56 is in a position to effect indexing of its associated reel 51. Thus, by the time the traveling brush has passed the contact 364, every pin fall registering device in the first player's line will register nine. However, none of the pin fall registering devices will, as yet, be visible since each device is covered by its associated shutter 135.

From the contact 364, the traveling brush passes to the contact 365. This contact is connected to a frame advance solenoid 160-L through a line which contains normally closed contact LX-9 associated with the strike recording mechanism and a normally closed contact L-7 associated with the spare recording mechanism. Since neither a strike nor a spare was scored in the first frame, both of these contacts LX-9 and L-7 will be closed so

as to enable a pulse to be transmitted to the solenoid 160-L. Energization of the solenoid 160-L will cause the operating bar 104-L to be pulled downwardly, thereby effecting rocking of the rock shaft 145 so as to lower the shutter 136 in the first frame. A downward pull on the operating bar 104-L causes rocking of the arms 152 and 156 so as to effect indexing of the shaft 145 the space of one tooth on the ratchet wheel 150. Such indexing of the shaft 145 will cause the first cam 147-1, that is, the cam associated with the pin fall registering device adjacent the first frame opening in the first player's line, to be rotated so as to cause its lobe 1 to bear against the roller bar 144 and lift the arms 141. Lifting of the arms 141 will, as has been pointed out, effect rocking of the shutter 136 downwardly and rocking of the arms 148 and the spanner bar 149 upwardly so as to lift the pull rods 56 and 56a, thereby exposing the numeral reels of the first frame and disconnecting them from further operation. At this point, the pin fall registering device associated with the first frame of player No. 1 will indicate a visible score of nine, but each of the remaining registering devices in that player's line will be obscured by its associated shutter means.

The next rotor contact engaged by the traveling brush 373 is contact No. 366 (FIGURE 60). This contact is connected to solenoid SZ-L associated with the back-off or reset unit 237 and the solenoid SZ-L is actuated each time the brush engages the contact 366. Energization of the solenoid SZ-L causes the operating bar 102-L to be pulled downwardly, thereby actuating the ratchet pawl 262 so as to move the latter in a direction which would cause the shaft 240 to be rotated counterclockwise, as viewed in FIGURE 47, the space of one tooth if the shaft 240 previously had been rotated clockwise. Since the apparatus is still concerned with the recording of the score attained in the first frame and since no strike or spare was rolled previously, the shaft 240 will not be in a position such that a tooth 260 of the cam 259 can be engaged by the pawl 262. Consequently, the movement of the pawl 262 at this stage accomplishes nothing.

Each of the rotor contacts 367 and 368 is connected to the solenoid SZ-L through a normally closed contact LX-10 associated with the strike recording mechanism. The contact LX-10 is closed at this stage of the game, inasmuch as no strike has been scored, so that back-off mechanism 237 is actuated once for each contact 367 and 368, although in each instance the movement of the pawl 262 accomplishes nothing.

The contact 369 is connected to the solenoid MSX-L which operates the strike recording apparatus 236, the circuit between the contact 369 and the solenoid MSX-L being controlled by a contact LX-11 which normally is open unless the strike lever LX has been closed. Since no strike was rolled in the first frame, the contact LX-11 will be open, so no action takes place upon engagement of the brush 373 with the contact 369.

The contact 370 is connected to the solenoid MS-L associated with the spare recording device 235 and the circuit between the solenoid MS-L and the contact 370 is controlled by a contact L-8 which is open except when the spare recording switch L-8 is closed. Since no spare was recorded in the first frame, the contact L-8 is open and no action takes place upon engagement of the brush with the contact 370.

The contact 371 is the last of the contacts on the disk 326 and when it is engaged by the traveling brush the scoring lever reset solenoid 26 is energized to return the depressed levers L to their neutral positions.

Across the power lines X and N is connected a relay RTO-L. This relay operates in conjunction with another relay RCT-L (FIGURE 61) which normally is energized through contact LS21L-3 of the switch L-21L or LS21R-3, depending on the position of the shift plate P-1, and through a pair of switches LS-11(1) and LS-12(1), except when scoring is to take place after the

tenth frame. This will be referred to subsequently but it is necessary to state at this point that the relay RTC-L has a contact RTC-1-L (FIGURE 60) which is closed as long as the relay RTC-L is energized. The relay RTO-L normally is inactive but may be energized through a normally open contact RTO-1 and through the normally closed switch LS-236. Since the contact RTC-L-1 is normally closed, engagement of the contact 371 by the traveling brush will energize the relay RTO-L so as to close the normally open contact RTOL-1 and complete a holding circuit to the relay RTO-L through the normally closed switch LS-236. Energization of the relay RTO-L prepares a circuit to effect turning of the shift plate cam shaft 118 by way of the solenoid 128-L, so as to restore the shift plate P-1 to its neutral position and to shift the second player's shift plate P-2.

From the contact 371, the traveling brush 373 returns to its neutral position between the contact 371 and 328 and the arm 374 engages and actuates the switch LS-54. Actuation of the switch LS-54 causes closing of a contact LS54L-3 (FIGURE 60) of the switch so as to complete a circuit through a closed contact RTOL-2 of the relay RTO-L and energize the solenoid 133 which, it will be recalled, operates to withdraw the latch bar 131 from the latch wheel 129 associated with the cam shaft 118. (See FIGURE 24.) A circuit is completed through the same elements to the solenoid 128 which operates the mechanism previously described to index the cam shaft 118 the space of one tooth on the ratchet wheel 123, or 36°. When the shaft 118 has been turned its full 36°, the switch LS-236 is opened, as described before, so as to de-energize the relay RTO-L, thereby de-energizing the solenoids 128 and 133. When the cam shaft 118 has been rotated 36° from its initial position, the shift plate P-1 will be released so as to be returned to its neutral position and the next shift plate P-2 will be in shifted position. Thus, the machine then is ready to record the score attained in the first frame by the second player of the team.

Similar circuitry including a contact LS54R-3 of the right hand rotor switch LS54R and a contact RTOR-3 of the corresponding right hand relay RTO-R is provided for actuating the solenoid 133a and the solenoid 128a associated with the cam shaft 119.

FIGURE 61 illustrates how the relay RTC-L for the left hand unit is energized. The circuit to this relay is made through the switch LS-12(1) having left and right contacts 12(1)L and 12(1)R and through a switch LS-11(1) having left and right contacts 11(1)L and 11(1)R and through one of the contacts of the limit switch LS-21L. Each player's line is provided with similar mechanism, the number of the particular line being indicated by the numeral in parentheses. The right hand relay RTC-R is shown in FIGURE 62 and is energized, for example, through switches LS-12(6) and LS-11(6) having sets of contacts 12L(6), 12R(6) and 11L(6), 11R(6), respectively, and one of the contacts of the switch 21R. It will be understood that the relay RTC-R is adapted to be actuated by mechanism similar to that just described associated with each player's line, the number of a particular line being represented by the number in parentheses.

Referring now to FIGURE 63, the apparatus for effecting operation of the team totals devices will be explained. As is shown, the solenoids 307 and 309 are operable to effect indexing of team No. 1 units and tens reels, respectively, by closing of the handicap switches 47 and 48. Similar solenoids 307a operate the units and ten numeral reels, respectively, of the second team total device under the influence of the handicap switches 47a and 48a. Manual operation of the switches 47-48a will enable handicaps to be set.

From the team No. 1 units solenoid 307 extends a line leading to one contact 211-1a associated with a contact LS211-1 of the switch LS-211 and from team No. 2 units solenoid 307a runs a line leading to another contact

211-1b of the switch LS-211-1. The switch LS-211-1 is connected to the power line X through a normally open contact RUL-2 of the left units relay RUL and which is closed upon actuation of the units relay RUL so as to send a pulse to the units solenoid 307. Thus, at the same time the pin fall registering devices 50 are indexed to record a score of nine, the relay 307 is energized to effect indexing of the team No. 1 totals unit nine times so as to increase by nine the score reflected by the team total device associated with team No. 1.

The switch LS211-1 has another contact 211-1b connected to the units solenoid 307a so as to be capable of operating the units reel of the total device for team No. 2 when the switch LS-211 has been shifted by the cam shaft 118. A similar arrangement is provided for connecting the switches LS211-2a and LS211-2b to the tens solenoids 309 and 309a for indexing the tens reels of the total device.

As has been indicated above, the No. 1 player of team No. 1 has scored nine pins in the first frame. This player ordinarily would not bowl again until each of his teammates has bowled. Then, the No. 1 player of team No. 1 would ordinarily bowl his second frame on the right hand alley, it being remembered that the first frame was bowled on the left hand alley. For the sake of simplification of explanation, however, only the scoring of player No. 1 on team No. 1 will be considered.

Assume that on the first ball of the second frame, player No. 1 falls six pins. He will therefore throw lever L-6-1 in the first ball column of levers L. Assume further that on the second ball, player No. 1 falls the remaining pins, thereby scoring a spare. He then will throw the spare lever L/. The opposing team member or neutral observer then will close the confirm switch 385 to set the traveling brush in motion. Since the game has progressed only to the second frame, all of the first ball levers L are isolated from the circuit, but a circuit is made to the driving motor through the switch L/ and through the appropriate permissive switch LS-21L of the second bank. When the brush reaches the first contact on the disk, contact No. 328, a contact L/1-1 (FIGURE 57) of the spare switch L/ will be closed so as to permit energization of the spare recorder solenoid S/L. The operating bar 193-L will, therefore, be pulled downwardly, causing rocking of the plate 193 to advance the mark bar 177 a distance sufficient to permit the second finger 186 to push the indicator plate 173 associated with the second window 41 a distance sufficient to enable the spare symbol to be visible through the window 41. The plate 173 will be latched in the spare indicating position by the cooperation of the latch bars 222 and 223.

The traveling brush passes by the next fourteen contacts without any action taking place, but when the brush engages contact No. 343, it energizes the solenoid 195-L to rotate the mark bar another 30° so as to condition it for use in operating the strike spare recorder associated with the third frame.

From the contact 343, the traveling brush passes each of the contacts 344-354 without any action taking place. When the brush engages contact No. 355, however, a circuit to the tens relay RT (FIGURE 57) now is completed by the closing of a contact L-6 of the switch L-1. Energization of the tens relay RT closes a normally open contact RT-1 (FIGURE 59) so as to energize the tens solenoid 114-L and effect indexing of each tens numeral reel 51 in player No. 1's line, except for the tens reel associated with the first frame, which reel has been disabled in the manner previously described. As a result of the indexing one space each tens reel, except the first, each pin fall registering device in line No. 1 will register nineteen, except for the first frame, which still indicates nine. Except for the first frame, however, all of the pin fall registering devices are obscured by their associated shutters.

No action takes place as the traveling brush engages each of the contacts 356-364, inasmuch as one of the levers L-1 through L-9 has been thrown.

It will be recalled that when the traveling brush previously engaged contact No. 365, the shutter in frame No. 1 was dropped and the associated pin fall registering device disabled. In the second frame operation, however, engagement of the brush with the contact 365 causes no action since the contact L-7 of the spare switch L/ now is open and prevents energization of the frame advance solenoid.

When the brush engages contacts 366-369, the actions of the back-off apparatus and the strike memory device are exactly as was previously described. When the brush engages contact 370, however, the contact L-8 now will be closed, due to the throwing of the spare switch L/, so as to effect energization of the solenoid S/-L and operation of the spare memory device 235 and consequent rocking 30° of the shaft 240. This will cause closing of the switch LS/ (see FIGURES 48 and 64), causing energization of the relay R/L through another of the contacts of a third bank of switch LS-21L. Energization of the relay R/L will close all of the relay's normally open contacts and open all of its normally closed contacts, which contacts will be referred to subsequently.

From the contact No. 370, the traveling brush proceeds as before to condition the apparatus to record the score attained by the second player in frame No. 2. At this stage we are concerned only with the score of the first player of team No. 1, so now assume that player No. 1 is ready to bowl in frame No. 3.

In frame No. 3, player No. 1 of team No. 1 falls six pins with the first ball and the remaining four pins with the second ball, scoring another spare. Thus, he manipulates lever L-6-1 in the first ball column of levers L and the spare lever L/. The machine now is ready to record the score for the third frame.

To recapitulate, it will be recalled that the pin fall registering device associated with frame No. 2 is obscured by the shutter and it, like each of the pin fall registering devices associated with the third through the tenth frames, registers nineteen. Referring now to FIGURE 57, the traveling brush 373, when actuated in the manner previously described, engages contact No. 328, and makes a circuit to the spare recorder solenoid S/L through the closed contact L-1 to actuate the mark bar and move the indicator plate 173 associated with the third window 41 to a position where it indicates a spare in the third frame. It will be recalled that lever L-6-1 in the column of first ball levers L was moved because six pins were knocked down on the first ball. It also will be recalled that the relay R/L is energized for line No. 1 so that each of that relay's normally open contacts now are closed. Consequently, when the traveling brush engages each of the contacts 329-334, a pulse will be sent to the units relay RU inasmuch as the contact R-1 associated with the first ball levers is closed. This will cause each of the units numeral reels in the second through the tenth frames to be indexed six spaces and it also will cause the associated team total device to be indexed so as to show an increase of six.

Nothing further takes place until the traveling brush engages contact No. 339. A circuit then is completed through a contact R/-3 to the frame advance solenoid 160-L which operates in the manner previously described to rotate the cam shaft 145 so as to open the shutter associated with frame 2 and disable the second frame's pin fall registering device. This device now will indicate twenty-five, or the sum of the pins knocked down in the first frame and the pins knocked down on the next succeeding three balls. Each of the pin fall registering devices associated with the third through the tenth frames also will register twenty-five, but they will be obscured by their associated shutters.

No further action takes place until the brush engages contact No. 343. A circuit then will be completed to the strike-space recorder solenoid 195-L to effect rotation of the mark bar another 30° so as to condition it for use in operating the strike-spare recorder associated with the fourth frame.

Since a spare was scored in frame No. 3, no action due to the engagement of the brush with the contacts following No. 343 takes place until the brush engages No. 355. Then the tens relay is energized, due to the fact that the spare switch contact L-6 is closed, so as to effect indexing of each of the tens reels of the pin fall registering devices in frames 3-10 and the team total device one space so as to add ten to the score. From the contact 355, the operation of the apparatus is exactly like that described in connection with the scoring of frame two and it is not believed necessary to repeat that description.

In frame No. 4, player No. 1 of team No. 1 scores a strike. As will be apparent from FIGURE 73, the strike follows immediately after a spare having been scored in the third frame. Under these conditions, when the traveling brush engages the first contact No. 328, a contact LX-1 associated with the strike lever LX has been closed and, as will be seen from FIGURE 57, a circuit then is completed to the strike recorder solenoid SXL. A circuit also is completed to the spare recorder solenoid through the contact L-1 which normally occupies the position shown in FIGURE 57, with the result that engagement of the brush with the contact 328 causes energization of both the strike and the spare recorder solenoids SXL and S/L. Consequently, both the mark bar actuating plates 198 and 208 are actuated simultaneously to move the mark bar a distance sufficient to enable the strike symbol to be visible through the window 41 associated with the fourth frame. The reason for actuating both the strike and the spare solenoids SXL and S/L, even though no spare was recorded in frame No. 4, is to permit the spare solenoid to assist the strike solenoid in moving the mark bar.

No further action takes place until the brush engages contact No. 338. At this point, a circuit is made to the tens relay RT, by reason of the strike switch contact LX-2 now being closed, to index each of the tens reels of the pin fall registering devices associated with frames 3-10 and the team total device tens reel one space so as to add ten to the score.

When the brush engages contact 339, a circuit is made through the contact R/-3 to the frame advance solenoid 160-L which operates to rotate the cam shaft 145 a distance sufficient to enable the cam 147-3 to open the shutter associated with frame 3 and disable that frame's pin fall registering mechanism. In frame 3, therefore, a score of forty-five will be indicated, which is the sum of the pins knocked down through the fourth frame. The pin fall registering devices associated with each of frames 4-10 also will indicate forty-five, but their shutters will prevent those devices from being seen.

From the contact 339 the brush proceeds to the contact 340 where a contact LX-3 associated with the switch LX is closed so as to enable a circuit to be completed through another contact R/-4 of the memory relay R/L to the tens relay RT so as to index each of the tens reels of the pin fall registering devices associated with the fourth through the tenth frames, and the team total device for team No. 1, so as to add ten to the score.

No further action takes place until the brush engages contact No. 343 so as to energize the strike-spare recorder solenoid 195-L and condition the mark bar for operating the strike-spare recording mechanism associated with the fifth frame.

Nothing further takes place until the brush engages contact No. 366, it being noted that engagement of the brush with the contact 365 did not effect opening of the

fourth frame's shutter, due to the fact that the contact LX-9 was open because the switch LX was thrown. When the brush engages the contact 366, the back-off device 237 is energized, backing the shaft 240 to its normal position.

The engagement of the brush with the contacts 367 and 368 does not effect operation of the back-off device 237 inasmuch as the normally closed contact LX-10 associated with the switch LX now is open.

When the brush engages contact No. 369, a circuit will be completed to the solenoid SX-L of the strike memory device 235 through a now closed contact LX-11 of the switch LX so as to effect rotation of the shaft 240 through 60°, thereby causing the cam 269 on the memory device 238 to be moved to a position where it closes the switch LSX. Upon the closing of the switch LSX, the relay RXL is energized through one of the contacts of the switch LS-21L. Upon the energization of the relay RXL, all of that relay's normally open contacts close and all of its normally closed contacts open. After the brush passes contact No. 369, no further scoring action takes place, except for the operation following engagement of the contact 371 as previously explained.

The condition of the apparatus opposite the first player's line of team No. 1 now is as follows: Each of the pin fall registering devices in frames Nos. 1, 2, and 3 is visible with the numeral 9 appearing in frame No. 1; the numeral 25 appearing in frame No. 2; and the numeral 45 appearing in frame No. 3. Each of the pin fall registering devices associated with frames 4-10 also will indicate the numeral 55, but the associated shutters prevent these pin fall registering devices from being visible. In each of frames No. 2 and 3, the spare symbol will be visible in the windows 41, whereas the strike symbol will be visible in the window 41 associated with the fourth frame.

In frame No. 5, player No. 1 of team No. 1 has an open frame, that is, he fails to score either a spare or a strike. For illustrative purposes, it will be assumed that he fells six pins on the first ball of frame No. 5 and three pins on the second ball, making a total of nine for the two balls. Since a strike was scored in frame No. 4, the nine pins felled in frame No. 5 must be added to the number of pins felled in frame No. 4, so that upon the opening of the shutter in frame No. 4, the score indicated in frame No. 4 will reflect the nineteen pins felled in frames Nos. 4 and 5.

Preparatory to recording the score in the fifth frame, the player manipulates the levers L in the column of first ball levers and in the column of second ball levers, the lever L-6-1 being moved in the first column and the lever L-9-2 being moved in the second column. Then the traveling brush may be made to move in the manner previously described. Neither a strike nor a spare having been scored in the fifth frame, no action takes place until the brush reaches contact No. 343, at which time the strike-spare recorder advance solenoid 195-L is actuated to rotate the mark bar 176 so as to condition it for use in the sixth frame.

As already has been explained, the relay RXL is energized by reason of player No. 1 having scored a strike in the preceding frame. Furthermore, the lever L-9-2 in the column of second ball levers has been moved so as to condition the establishing of a circuit through the contact L-1-b et seq. of the switch L-9. Consequently, when the traveling brush engages contact No. 344, a circuit is completed to the units relay RU through a contact Rx-1 of the relay RX. The completion of this circuit will, as has been pointed out earlier, cause indexing of the units numeral reel of each pin fall registering device in line 1 that has not been disabled, and indexing of the units reel of the total device for team No. 1. Thus, as the brush engages each of the contacts 344-352, the numeral reels of the pin fall registering devices obscured

by the shutters, and the units reel of the team No. 1 total device will be indexed to add nine to the score.

When the brush engages contact No. 353, nothing takes place inasmuch as no spare has been recorded, but 5 when the brush engages contact No. 354, a circuit is completed through the switch contact LX-5 of the switch LX and through a contact RX-3 of the relay RX-L to complete a circuit to the frame advance solenoid 160-L so as to effect opening of the shutter associated with 10 frame No. 4 and to disable the pin fall registering device associated therewith. At this stage, a total of nineteen will have been added to the score previously registered by the pin fall registering device associated with frame No. 4 so that when the shutter is opened a total of sixty-four 15 will be indicated in frame No. 4.

When the traveling brush reaches the second bank of second ball switches (FIGURE 59) associated with the contacts 356-364, the units numeral reels of each of the pin fall registering devices associated with frames 5-10 20 and the units reel of No. 1 team's total device will be actuated to add nine to the score. When the brush engages contact 365, the frame advance solenoid 160-L again will be actuated, since neither a strike nor a spare was recorded in frame No. 5, so as to open the shutter 25 associated with frame No. 5. The score indicated by the pin fall registering device associated with frame No. 5 now will indicate nine more than the score indicated in frame No. 4, or seventy-three.

As the traveling brush engages each of the contacts 366, 367, and 368, the back-off device 237 will be actuated in the manner previously described so as to tend to rotate the shaft 240 through 90° in a counterclockwise direction. Since the shaft 240 had been rotated only 60° in the clockwise direction, however, it can be returned only a total of 60°, but this amount of movement will restore the memory device 238 to its initial or neutral position, thereby breaking the circuit to the relay RXL and restoring its contacts to their normal conditions.

From the contact 368, the action of the apparatus is 40 exactly the same as was described in connection with frame No. 1.

In frame No. 6, player No. 1 of team No. 1 scores a strike. The action of the machine, following the movement of the traveling brush, is as follows: Engagement 45 of the brush with the contact 328 registers a strike symbol in the window 41 associated with the sixth frame, and engagement of the brush with the contact 338 effects operation of the tens relay to index one space the tens numeral reel of the No. 1 team's total device and each of 50 the pin fall registering devices associated with frames Nos. 6-10. Engagement of the brush with the contact 343 rotates the mark bar 176 to condition it for operation of the strike spare mechanism associated with frame No. 7. Engagement of the brush with the contact 369 55 effects operation of the memory device 238 through the contact LX-11 to close the switch LSX and energize the relay RXL as has been explained previously. The result of the action just described is that each of the pin fall registering devices associated with frames No. 6-10 60 indicates a score of eighty-three, but these devices are not visible because the shutters remain closed. Also, the strike symbol associated with frame No. 6 is recorded.

In frame No. 7, player No. 1 scores a spare, knocking down six balls, for example, on the first ball and four on 65 the second ball. Since a player who scores a strike is entitled to receive credit in the frame where the strike was scored not only for the ten pins knocked down but also for the sum of the pins knocked down on the succeeding two balls, player No. 1 should have a total of twenty added to his previous score. It will be recalled, 70 however, that the pin fall registering device associated with frame No. 6 already has had ten added thereto, so it is necessary to add only ten more. This is accomplished in the following manner: engagement of the brush 75 373 with contact No. 328 will effect operation of

the spare recording solenoid S/L to have the spare symbol associated with frame No. 7 moved into position in window 41. Engagement of the brush with the contact 343 will move the mark bar 176 into position to actuate the strike-spare mechanism associated with frame No. 8. Engagement of the brush with the contact 353 will cause a circuit to be completed through the contact L/5 and a contact RX-2 of the relay RXL to the tens relay RT to effect indexing one space each of the tens numeral reels associated with the pin fall registering devices in each of frames Nos. 6-10 and with the tens reel of the No. 1 team's total device so as to add ten more to the score. Engagement of the brush with the contact 354 will enable a circuit to be completed to the frame advance solenoid 160-L through the contact LX-5 and the contact RX-3 so as to open the shutter associated with frame No. 6 and disable its pin fall registering mechanism. Engagement of the brush with the contact 355 adds ten to frames Nos. 7 through 10 which are covered by their shutters. Engagement of the brush with contacts 366-368 will effect a return of the memory device 238 to its inactive position, but engagement of the brush with the contact 370 will set the memory device 238 in such position that the switch LS/ is closed. Further movement of the brush results in operations like those previously described in connection with the scoring of a spare.

In frame No. 8, it will be assumed that player No. 1 of team No. 1 scores a strike. Since he scored a spare in frame No. 7, the score to be recorded in frame No. 7 should be twenty more than the score recorded in frame No. 6. As the brush engages contact No. 328, the strike and spare solenoids SXL and S/L are operated to record a strike in frame No. 8. When the brush engages contact No. 338, the tens relay RT is actuated to index the tens reel of the pin fall registering devices associated with frames Nos. 7-10 one space, with corresponding indexing of the tens reel of the No. 1 team's total device. At this time, the pin fall registering devices associated with each of frames Nos. 7-10 and with the team total device will indicate a score of 113.

When the brush engages contact No. 339, the frame advance solenoid 160-L is actuated through the contact R/-3 to shift the shutter associated with frame 7 and disable its pin fall registering device. Thus, frame 7 will indicate a visible score of 113.

Upon engagement of the brush with the contact No. 340, the tens relay RT will be energized through a strike contact LX3 associated with the strike lever LX and through a contact R/-4 associated with spare relay R/. Energization of the tens relay will, as has been pointed out previously, index the tens reel of the shuttered pin fall registering devices and the tens reel of the No. 1 team's total device one space to add ten to the score of each.

Upon engagement of the brush with the contact 366, the back-off device 237 is actuated once to break the circuit to the relay R/L through the switch LS/. Engagement of the brush with the contacts 367 and 368 does not effect operation of the back-off device 237 since the strike contact LX-10 will now be open. The strike contact LX-11 will be closed, however, so the engagement of the brush with the contact 369 will actuate the solenoid SX-L to operate the memory device 238 in such manner as to cause the switch LSX to be closed, thereby making a circuit to the relay RXL. Nothing further takes place except for the resetting of the levers L upon engagement of the brush with the contact 371.

Assume that in frame No. 9, player No. 1 on team No. 1 scores a strike. This is the second strike in succession. Movement of the brush 373 into engagement with the contact 328 will therefore cause the strike symbol associated with frame No. 9 to be recorded and engagement of the brush with the contact 338 will cause the tens relay RT to be operated so as to add ten to the pin fall registering devices associated with each of the frames Nos. 8-10

and with the No. 1 team's total device. At this point, the score indicated by the pin fall registering device associated with frame No. 8 will be twenty more than the score indicated in frame No. 7, or one hundred thirty-three. This score is not visible, however, since the shutter in frame No. 8 is still closed. The addition of ten to the score in frame No. 8 is not the total score possible to be obtained in frame No. 8, however, since a player who rolls a strike is entitled to be awarded the sum of the pins knocked down on the next succeeding two balls. Consequently, the opening of the shutter in frame No. 8 must be delayed until the player has an opportunity to roll another ball.

No action takes place following engagement of the brush with the contact 338 until the brush engages contact 343, at which time the mark bar 176 is advanced to be in condition to record the rolling of a strike or spare in frame No. 10. Nothing further takes place until the brush engages contact No. 366, at which time the back-off device is returned 30°, but even so, the memory shaft remains advanced 30° from its neutral position. Engagement of the brush with the contacts 367 and 368 has no effect due to the contact LX-10 being open, but its engagement with contact 369 advances the memory shaft an additional 60° for a total of 90°. The memory device cam lobe 269 now engages and closes the switch LSXX and as a result the relay RXXL is energized. Nothing further takes place except for the resetting of the levers L.

In frame No. 10 it will be assumed that player No. 1 fells six pins on the first ball and three pins on the second ball. Accordingly, he will depress the lever L-6-1 associated with the column of first ball levers L and lever L-9-2 associated with the column of second ball levers. Under these conditions, engagement of the brush with the contact 328 will not effect any action of the mark bar 176. Engagement of the brush with the first six contacts 329-334 of the bank of first ball contacts associated with the contacts 329-334 will cause a succession of six pulses to be transmitted to the units relay RU through a contact RX-1 associated with the relay RX. This will cause the units reels of the pin fall registering devices associated with each of frames Nos. 8, 9, and 10 to be advanced six spaces and a corresponding movement of the units reel of the No. 1 team's total device, thereby adding six to the total of each. That is, the score now under the shutters in frames Nos. 8, 9, and 10 is one hundred thirty-nine.

When the brush engages contact No. 339, a circuit is completed to the frame advance solenoid 160-L through a second contact RX-2 associated with the relay RX so as to open the shutter associated with frame No. 8 and disable its pin fall registering device. At this time, the pin fall registering device associated with frame No. 8 and with each of frames Nos. 9 and 10 indicates a score of one hundred thirty-nine.

When the brush engages contact No. 341, a circuit is made through a third contact RX-3 to the tens solenoid RT so as to index one space the tens reel of the pin fall registering devices associated with frames Nos. 9 and 10 and with the No. 1 team total unit, so that these units indicate a score of one hundred forty-nine.

Upon engagement of the brush with the contact 343, the mark bar 176 is rotated and the result of this will be explained hereinafter.

It will be recalled that six pins were felled by the first ball rolled in frame No. 10 and three pins felled by the second ball rolled in frame No. 10. Accordingly, the lever L-9-2 associated with the column of second ball pins will have been depressed and the contact L-9-2 closed. Consequently, engagement of the brush with each of the contacts 344-352 will effect, through a fourth contact RX-4 of the relay RX, energization of the units solenoid so as to advance the units reels of the pin fall registering devices associated with each of frames No. 9

and 10 and with the No. 1 team's total device nine spaces to add a total of nine to each. At this time, each of frames No. 9 and 10 will indicate a score of 158, but this score will not be visible because of the shutters.

When the brush engages contact No. 354, a circuit is completed to the frame advance solenoid 160-L through the normally closed strike contact LX-7 and a fifth contact RXX-5 associated with the relay RXX. This will open the shutter associated with frame No. 9 and disable its pin fall registering mechanism so as to permit the score of one hundred fifty-eight to be visible.

Engagement of the brush with each of the contacts 356-364 will cause indexing of the units reel of the tenth frame pin fall registering device so as to add nine to the score to be recorded in frame No. 10 and a corresponding operation of the team No. 1 total unit. The score now recorded in frame No. 10 is one hundred sixty-seven, but the pin fall registering device associated with frame No. 10 is not visible because the shutter is still closed. Upon engagement of the brush with the contact 365, however, a circuit is made through the normally closed contacts LX-9 and L-7 to the frame advance solenoid, whereupon the shutter associated with frame No. 10 is opened and its pin fall registering device disabled. The score recorded in frame No. 10 will now be visible and that score is the total score achieved by the player for the entire game.

When the brush engages contact 366, the back-off device 237 is operated by the solenoid SZ-L to set the memory device 238 on the switch LSX, then on the switch LS/, and finally in its initial position.

Upon the opening of the shutter associated with the tenth frame, all further scoring operations in the first player's line are complete and the scoring devices associated therewith are disconnected from the circuit. This takes place by the closing of a normally open switch LS-10FL-1 (see FIGURES 12 and 60) mounted on an arm 141a of each tenth frame shutter actuator, there being one such switch for each of the tenth frame scoring devices. The switches LS-10FL are indicated in FIGURE 60 and are marked with the subscript 1, 2, 3, etc., to indicate the switches associated with the first, second, third, etc., players' lines. The closing of the switch LS-10FL₁ energizes a relay R10FL having normally closed contacts R10FL₁, R10FL₂, and R10FL₃ (FIGURE 57) located respectively in the lines leading to the frame advance relay 160-L, the tens relay RT, and the units relay RU. These contacts open upon energization of the relay R10FL. When these contacts are open, no further scoring action can take place in line 1.

The relay R10FL includes another contact R10FL₄ (FIGURE 60) located in a wire bridging the contact 371 and the relay RTO. The contact R10FL₄ normally is open, but closes upon energization of the relay R10FL so as to be capable of supplying power to the relay RTO from the contact 371 following opening of the tenth frame shutter. The function of the relay RTO, it will be recalled, is to effect a switching operation to permit operation of the scoring mechanism in successive lines. Thus, after the final score has been registered in the tenth frame and the associated shutter opened, engagement of the traveling brush with the contact 371 will switch the scoring mechanism to the second player's line, and so on.

Tenth frame spare

The recording of the score in the tenth frame just described is the most simplified of all possibilities because neither a strike nor a spare was scored by player No. 1. In many instances, however, the player will score either a strike or a spare in the tenth frame so as thereby to be entitled to roll two additional balls or one additional ball, respectively. For example, assume that the player scored a spare with the second ball rolled in frame No. 10. He then would be entitled to roll an

additional ball and the number of pins felled with that additional ball would be added to the player's score and be recorded in frame No. 10. An example of such an instance is illustrated in FIGURE 74, wherein the player scored a spare in frame No. 10. As will be apparent from FIGURE 74, when the player began the tenth frame he had just completed scoring two successive strikes in the preceding two frames, so the number of pins felled by the first ball rolled in the tenth frame would be added to the score to be recorded in frame No. 8, and the sum of the pins felled in the tenth frame would be added to the total score recorded in frame No. 8 to arrive at the score to be recorded in frame No. 9. Prior to discussing the scoring in the tenth frame, it will be assumed that the player's total score to be recorded in the ninth frame is one hundred forty-nine and that the player felled six pins with the first ball in the tenth frame and four pins with the second ball, thereby scoring a spare and entitling the player to roll one additional ball. Had no spare been recorded in the tenth frame, the tenth frame shutter would have opened upon engagement of the traveling brush 373 with the contact 365. In order to record an additional score upon the scoring of a spare in the tenth frame, therefore, it is necessary to disable opening of the tenth shutter frame at the time it normally would open.

It will be recalled from the prior discussion of the recording of the scoring in the tenth frame of the first player that the tenth frame shutter opened upon engagement of the traveling brush with the contact 365. Inasmuch as the second player scored a spare in the tenth frame, however, the normally closed switch contact L-7 associated with the contact 365 will be open, thereby breaking the circuit to the frame advance solenoid 160-L. Consequently, engagement of the brush with the contact 365 will not open the tenth frame shutter of the second player's line.

Following the action of the traveling brush 373 from the contact 343, it will be apparent from the description 40 which has gone heretofore that no action takes place until the brush 373 engages contact 353. At this time, a circuit is completed from the contact 353 through the contact L-5 and the contact RXX-6 to the tens relay RT so as to add ten to the score indicated by the indicia in both the ninth and tenth frames, the score being added to the ninth frame because the score to be recorded in that frame must include the sum of the pins felled in the tenth frame inasmuch as a strike was scored in the ninth frame. Thus, the indicia associated with both the ninth and tenth frames will reflect a score of one hundred forty-nine.

When the traveling brush engages contact 354, a circuit is completed through the contact LX-5 and the contact RXX-5 to the frame advance solenoid 160-L to lift the shutter associated with the ninth frame in the manner previously described.

Upon engagement of the traveling brush with the contact 355, a circuit is made through the contact L/6 to the tens solenoid to add ten more points to the score 60 to be indicated in the tenth frame, all of these additions to the score also being added to the team total. Engagement of the traveling brush with the contacts 356-364 has no effect as none of the scoring levers associated with those contacts has been closed inasmuch as a spare was recorded in the tenth frame. Since a spare was recorded for the tenth frame, the switch contact L/7 is open, so nothing takes place upon engagement of the traveling brush with the contact 365.

Engagement of the brush with the contacts 366-368 70 effects operation of the back-off solenoid SZ-L in the manner previously described, and engagement of the traveling brush with the contact 370, actuates the spare solenoid S-L to advance the spare memory device 30° in the manner previously described. Normally, upon engagement of the traveling brush with the contact 371,

the levers L are reset and the relay RTO is energized through the normally closed contact RTC-1. At this point, however, the contact RTC-L-1 will be open (as is the contact RFL10₄) and no circuit can be made to the relay RTO. Accordingly, the shift plate P associated with the player scoring the spare in the tenth frame remains in its shifted position and that player is enabled to roll another ball.

It is convenient at this point to describe the operation of the contact RTC-L-1 and its associated parts. The contact RTC-L-1 is operated by a normally energized relay RTC-L (see FIGURE 61) that normally is energized through contacts 12(1)L and 11(1)L of the switches LS-12(1) and LS-11(1), respectively. As is shown in FIGURES 61 and 62, there are switches LS-11 and LS-12 for each player's line, and the particular line with which switches are associated is indicated by the subscript (1), (2), (3), etc. At present, this discussion is concerned with the second player's line, or with the switches LS-12₍₂₎ and LS-11₍₂₎.

It was pointed out earlier in the discussion of the recording of the scoring in the tenth frame of the second player of team No. 1 that the mark bar was rotated in the usual manner. Such rotation of the mark bar, however, causes the cam 230 (FIGURE 41) to engage the blade of the switch LS-11(2) and shift it off the contact 11(2)L onto the contact 11(2)R. As long as the blade of the switch LS-11(2) remained on the contact 11(2)L, a circuit was completed to the relay RTC-L through a contact LS-22-L-3 of the switch LS-22L. Upon shifting of the switch blade to the contact 11(2)R, however, the circuit to the relay RTC-L is broken inasmuch as the contact R/-5 now is open due to the operation of the spare relay R/-L. At this time, both the contact RTC-L-1 and R10FL4 will be open so as to prevent shifting of the scoring mechanism to the third player's line. Shifting of the switch blade to the contact 11(2)R completes a circuit through a contact LS22-L-4 of the switch LS-22-L so as to energize a relay R-11-L (FIGURE 61). Energizing of the relay R-11-L closes a normally open contact R11-L-1 associated with the first ball switches L (see FIGURE 56), whereupon closing of any of the first ball switches will condition to circuit to the traveling brush for operation.

As is indicated in FIGURE 74, it has been assumed that the second player on team No. 1 fells nine pins with the extra ball permitted after scoring a spare in the tenth frame. The player therefore manipulates the lever L-9-1 of the first ball levers to indicate the nine pins and, upon closing of the confirm switch 385, the traveling brush begins to move. Engagement of the brush with the contact 328 causes no action since there is no circuit to the strike or spare recorders. Upon engagement of the brush with the contacts 329-336, however, the units relay is actuated nine times through the contact R/1 and through the closed contact R10FL3. Thus, nine more points are added to the score to be indicated by the tenth frame indicating means. The numeral reels associated with the tenth frame now indicate one hundred sixty-eight, but the shutter remains closed.

When the traveling brush engages contact 339, a circuit is made through the contact R/3 and the closed relay contact R10FL1 to advance the frame and open the shutter of the tenth frame. Opening of the tenth frame shutter effects energization of the relay R10FL, in the manner indicated, energizing the relay thereby disabling further scoring in the second player's line. With the relay R10FL energized, the circuits to the units relay, the tens relay, and the frame advance relay are broken and therefore, with two exceptions, contact of the traveling brush with any of the stationary contacts associated therewith will have no effect.

The first of the two exceptions referred to occurs when the traveling brush engages the contact 343. When this occurs, the mark bar 176 will be advanced or rotated

the space of one finger 136 which will cause the cam 231 (FIGURE 42) to engage the switch LS-12(2) (FIGURE 61). The significance of this will be explained herein-after. The second exception referred to occurs when the traveling brush engages contact 371, at which time a circuit is made to the relay RTO to actuate the shift plate shifting mechanism and condition the scoring mechanism for the next bowler. In this case, the circuit is from the contact 371 through the normally open but now closed contact R10FL4 of the relay R10FL to the relay RTO.

Tenth frame strike

It not infrequently happens that a player is entitled to roll more than one ball following completion of the tenth frame. Thus, if a strike is scored in the tenth frame, the player is permitted to roll two additional balls. Should he score either a spare or a strike in the eleventh frame, the scoring will be different from that just described. Accordingly, an example of scoring a spare in the eleventh frame will be presented.

FIGURE 75 indicates a portion of a typical game wherein the third player on team No. 1 scored strikes in each of frames eight, nine, and ten and a spare in the eleventh frame. As is shown, the spare symbol appears in the eleventh frame window, and the manner in which the symbol is caused to appear is the same as has been described herebefore.

It will be assumed that in scoring the spare six pins were felled by the first ball in the eleventh frame and four pins were felled by the second ball. The scoring apparatus will be conditioned exactly as in the previously described situation where the second player on team No. 1 scored nine in the eleventh frame, except that, in the present instance, the lever L-6 associated with the first ball switches is actuated and the spare lever associated with the second ball levers is actuated. When the scoring action is begun, the memory device 238 will be set on the switch LSxx so that the contact Rxx-7 (FIGURE 61) will be open, thereby preventing energization of the relay RTC-L. The relay R11-L will not be energized at this time. As soon as the traveling brush engages the contact 328 the spare solenoid S/L causes a spare symbol to appear in the eleventh frame window 41. As the scoring in the eleventh frame is begun, the score behind the ninth and tenth frame shutters is 153, and a score of 133 is visible in the eighth frame. The first six pins to be recorded are added to the score as the traveling brush engages the contacts 329-334. Thereafter, the score to be recorded in the tenth frame is increased by operation of the apparatus in the manner previously described.

FIGURES 73-81 represent every conceivable possibility which could arise at the end of ten frames of bowling. Thus, the apparatus is capable of recording accurately in the tenth frame the score to be accumulated in the tenth, eleventh, and twelfth frames for all of these conditions. It is not believed necessary to describe each possible scoring condition, but one more illustrative example will be described, namely, one in which a player's score carries forward to the twelfth frame.

Twelfth frame scoring

FIGURE 77 assumes a case wherein a player scored a spare in the seventh frame, strikes in each of the eighth, ninth, and tenth frames, a strike with the first ball rolled following the tenth frame, and nine pins with the second ball or the twelfth frame ball. Let it be assumed further that the player attained a total of one hundred three points in the seventh frame. Under these conditions, the shutters associated with frames, eight, nine, and ten are closed and each of the scoring indicia behind those shutters will indicate one hundred three, due to the scoring of the spare in the seventh frame. When each strike is scored in the eighth and ninth frames, ten additional points will be added to each of the numeral reels associated with the eighth, ninth, and tenth frames, but they will not be visible until the number of pins felled with

the first ball in the tenth frame has been recorded. The scoring of the game illustrated in FIGURE 77 will be described beginning with the first ball in the tenth frame.

It will be noted that the player scored a strike in the tenth frame, which means that only one ball was thrown. Thus, the rotor will be started in the manner previously described so as to cause the traveling brush to engage each of the rotor contacts as has already been discussed. Engagement of the brush with contact 328 causes the mark bar 176 to record the strike symbol in the tenth frame window. No further action takes place until the brush engages contact 338, at which time ten points are added to the numeral reels in frames eight, nine, and ten, contact being made to the tens relay RT through the contacts LX-2 and R10FL2. At this time each of the numeral reels associated with eighth, ninth, and tenth frames will indicate 133, but they will not be visible because the shutters are closed. Engagement of the traveling brush with contact 339 energizes the frame advance relay 160-L through the contact RXX-2 (two previous strikes having been scored), thus opening the eighth frame shutter and exposing the eighth frame score.

Engagement of the traveling brush with each of the contacts 341 and 342 adds a total of ten more points to each of the numeral reels associated with the ninth and tenth frames so that each of those scoring devices indicates one hundred fifty-three, but the score is obscured by the shutters.

Engagement of the traveling brush with the contact 343 advances the mark bar 176 to the eleventh frame, actuating the switch LS11(5) and de-energizing the relay RTC-L and opening the contact RTC-L-1 since the RXX-7 is open. The relay R-11-L remains de-energized inasmuch as the contact R-6 of the spare memory device remains open. No further action takes place until the traveling brush engages the contact 366, at which time the solenoid SZ-L is actuated to back off the memory device 238 30°. Engagement of the traveling brush with the contact 369, however, actuates the solenoid SX-L to advance the memory device 30° or back to the double strike indicating position. Engagement of the traveling brush with the contact 371 accomplishes nothing inasmuch as the normally closed contact RTC-L-1 is now open because of the de-energization of the relay RTC-L in the manner previously described. Accordingly, the rotor comes to a stop without shifting the shift plate associated with the fifth player on team No. 1 from its activated position.

Since the particular player under consideration scored a strike in the tenth frame, he is entitled to complete his game and will roll two additional balls. As is indicated in FIGURE 77, it has been assumed that he scored a strike with the first ball in the eleventh frame. Thus, the traveling brush may be actuated in the manner already described so as to cause the brush to engage the contact 328 to actuate the mark bar 176 and record a strike symbol in the eleventh frame window. Upon engagement of the traveling brush with contact 338, ten additional points are added both to the ninth and tenth frame scoring devices so that each of them indicates 163.

Engagement of the traveling brush with the contact 339 opens the ninth frame shutter, exposing the ninth frame score. Engagement of the traveling brush with each of the contacts 341 and 342 adds ten more points to the numeral scoring indicia associated with the tenth frame, so that the latter now indicates one hundred eighty-three. Engagement of the brush with the contact 343 advances the mark bar 176 to the twelfth frame, thereby actuating the switch LS12(5) to shift the latter from a contact 12(5)L to a contact 12(5)R (see FIGURE 61). The relay R12-L thus becomes energized and its normally open contact R-12-L-1 (see FIGURE 56), closes.

No further action takes place until the traveling brush engages the contact 366, at which time the memory de-

vice 238 is backed off 30°, but the memory device is re-advanced 30° upon engagement of the traveling brush with the contact 369. Engagement of the traveling brush with the contact 371 causes no action to take place inasmuch as the relay RTC-L remains de-energized, due to the shifting of the switch LS-12(5). Accordingly, the apparatus does not shift to record the score of the next player, but remains in condition to permit the player under consideration to roll one additional ball.

In the present example it has been assumed that the player felled nine pins with the second ball rolled after the tenth frame, i.e., the first ball in the twelfth frame. Thus, the lever L-9-1 associated with the first ball scoring levers will be depressed. Upon depression of the lever L-9-1 a circuit can be completed, upon closing of the confirm switch 385, through the relay contact R-12-L-1 so as to start the traveling brush. Engagement of the brush with the contact 328 accomplishes nothing since the switch LX-1 is open. Engagement with each of the contacts 329 through 337 causes a total of nine to be added to the units reel associated with the tenth frame scoring device so that the score indicated thereby will be 192. Engagement of the brush with the contact 339 opens the tenth frame shutter and actuates the limit switch LS10FL so as to energize the relay R10FL and prevent any further scoring in the tenth frame. Finally, engagement of the traveling brush with the contact 371 will cause the player's shift plate to be returned to its neutral position, thereby completing the scoring for that player.

It is believed that the operation of the scoring mechanism will be understood fully from the foregoing description of parts of several typical games without requiring further description.

Reseat at end of game

When all of the players on one team have completed their games it is necessary to reset the scoring apparatus in order that additional games by the team members may be scored. In resetting the apparatus, all of the shutters must be closed, all of the pin fall registering devices must be returned to zero, the team total devices must be returned to zero, all of the strike-spare windows must be closed, and the memory devices must be restored to their neutral positions.

Reset Mechanism

The reset mechanism includes the manually operated switch button 46 (FIGURE 65) arranged in parallel with a switch LS-425 to start a reset motor 425 (FIGURE 66). The motor shaft drives a gear reduction unit 427 which in turn drives a shaft 428. The shaft 428 drives a shaft 429 through pulleys 430, 431, and a belt 432. Mounted on the shaft 429 is a cam 433 having a lobe 434 (FIGURE 69) which normally maintains the switch LS-425 open. Consequently, it is necessary to hold the button 46 down manually for a sufficient length of time to enable the cam lobe 434 to clear the switch LS-425, at which time the switch will remain closed until it once again is opened by a complete revolution of the cam 433. This is desirable so as to prevent inadvertent resetting of the apparatus.

As is indicated in FIGURE 65, the closing of the reset button 46 not only actuates the reset motor 425 but also energizes two solenoids, 435 and 436. Energization of the solenoid 435 operates a linkage 437 (FIGURE 70) including a rock shaft 453 that is rocked to remove a locking finger or arm 438 from a notch 439 in the cam 433, thereby permitting the cam 433 to rotate with the shaft 429. When the solenoid 435 is deenergized, a spring 440 acts on the linkage 437 to restore the arm 438 to its locking position.

Resetting pin fall registering and team total devices

The diameters of the pulleys 430 and 431 are so related to one another that the shaft 428 makes 13 revolu-

tions for each revolution of the shaft 429. The one revolution of the shaft 429 is used to reset all of the pin fall registering devices and the team total devices numeral reels to zero. Referring to FIGURE 71, the shaft 429 is located at the bottom of the housing and is provided with a sprocket wheel 441 that is drivingly connected by a chain 442 to sprocket wheels 433 mounted on each of the numeral reel shafts 52. It will be remembered that each of the numeral reels 54 is mounted on its shaft 52 for rotation relative thereto and that the centering roller devices 74 are fixed on the shafts 52 for rotation therewith. During the resetting of the numeral reels, however, the shafts 52 are to be rotated counterclockwise, as viewed in FIGURE 15, until such time as the centering devices 74 again are placed in their upper, vertical positions. As the shafts 52 are rotated from the drive shaft 429, the reels 54 are rotated with the shafts, due to the engagement of the roller 74 with the pins 55. As the shafts 52 rotate, the numeral reels 54 will rotate therewith until such time as a peg 445 on the inner periphery of each reel (see FIGURE 14) engages a pawl 446 that is rockably mounted on a stub shaft 447 projecting rearwardly from the front wall of the housing. Also mounted on each stub shaft 447 is an arm 448 to which is connected a spring 449 which constantly urges the arm 448 in such direction as to cause the pawl 446 to lie in the path of the peg 445. The normal position of the pawl 446 is determined by a stop 450 mounted on the wall of the housing in a position to engage the arm 448.

The construction and arrangement of the parts just described are such that, when the numeral reels are being actuated during their recording of a score, the pegs 445 are capable of displacing the pawls 446 so as to permit rotation of the reels past the pegs. Upon rotation of the numeral reels in the opposite direction during reset, however, the pawls 446 serve as holding means for the numeral reels upon engagement between the associated pegs and pawls so as to permit relative movement between the shafts 52 and their numeral reels during resetting operation. The positions of the pegs 445 are so selected as to assure the numerals zero being aligned with the frame window openings.

The arrangement for zeroing the numeral reels of the team total devices is the same. As is shown in FIGURES 49 and 50, the shaft 52 that is associated with the fifth player's line on team No. 1 is coupled to the shaft 300 by a chain 300a that is trained around a sprocket 300b fixed on the shaft 300 and a similar sprocket fixed on the shaft 52. Thus, the shaft 300 rotates with the shafts 52. A similar arrangement is provided for the total device associated with the No. 2 team, but the latter is driven from the shaft 52 associated with the line of the last player on that team.

As has been pointed out earlier, the closing of the reset circuit energized a solenoid 436. The solenoid 436 has its plunger 451 (see FIGURE 71) connected to an operating rod 452 to which are pivoted ten operating levers 453. Each of the operating levers 453 is fixed to a shaft 454 associated with a row of scoring devices and on each of the shafts 454 is fixed a tab 455 that is adapted to be flipped upwardly upon actuation of the operating rod 452 so as to cause the tabs 455 to bear against the actuating bars 56 and 56a (see FIGURES 10 and 11) and prevent their being dropped during resetting of the numeral reels to zero. Upon de-energization of the solenoid 436, the operating rod 453 and its associated parts are returned to their normal positions by a spring 456 (see FIGURE 71).

For disconnecting the actuating bars 304 and 305 from the team total device numeral reels, the fifth shaft 454 has keyed thereto a lever 454a (see FIGURE 49). The lever is pivoted to one end of a link 454b, the other end of which is pivoted to a lever 315a that is keyed to the shaft 315. The arrangement is such that rocking of the

lever 454 in the manner described above causes corresponding rocking of the lever 315 so as to flip upwardly the tab 314 and lift the bars 304 and 305 so as to permit the numeral reels of the total device to be rotated to their zero positions. The same kind of apparatus is provided for the total device for team No. 2, and operates off the tenth shaft 454.

Strike-spare recorder reset

- 10 Resetting of the strike-spare recorder devices 170 is initiated with the energization of the solenoid 435 which, as has been indicated, causes rocking of the shaft 458 (FIGURE 70) so as to remove the finger 438 from latching engagement with the wheel 433. Referring to FIGURE 72, rocking of the shaft 458 causes a corresponding rocking of a lever 459 that is keyed to the shaft 458 and the lever 459 is attached by a link 460 to a bell crank 461 which, in turn, is pivoted to a rod 462 supported in guides 463 and normally urged upwardly by a spring 464.
- 15 The rod 462 is connected to each of the bars 228 by bell cranks 465 in such manner that downward movement of the rod 462 causes movement of all the bars 228 to the right, as viewed in FIGURE 72. Such movement of the bars 228 will cause their projections 227 (see FIGURE 25 34) to effect disengagement of the associated pawls 222 from the slides 173 and permit the latter to be returned to the normal or non-indicating position by their return springs 175.

Mark bar reset

- 30 Resetting of the mark bar 176 is effected from a crank shaft 466 (FIGURE 66) which is driven by a chain or belt 467 from the shaft 428 and preferably at the same speed as the latter so as to make thirteen revolutions during the reset cycle. On the crankshaft 466 is journaled one end of a connecting rod 468 (see FIGURE 43), the other end of which is pivoted to a linkage 469 that in turn is pivoted to a vertically reciprocable bar 470. The bar 470 is operatively connected by means of studs 471 to a lever 472, pivoted as at 473 on the housing 178 so that vertical movement of the bar 470 causes oscillating movement of the lever 472 about the axis of the pivot 473. The lever 472 is provided with a spring biased pawl 474 adapted to engage a toothed wheel 475 fixed on the shaft 177, the arrangement being such that oscillation of the lever 472 and pawl 474 enables the wheel 475, and the shaft 177, to be indexed tooth by tooth. The wheel 475 is provided with eleven teeth, but has sufficient space to accommodate twelve teeth. The missing tooth space is so located on the wheel that when the pawl is received in the space all of the fingers 186 of the mark bar will be in their original or starting positions. When the pawl encounters the missing tooth space, it is prevented from indexing the wheel 475 any further. Accordingly, thirteen oscillations of the lever 472 will be more than enough to assure resetting of the mark bar.

Closing the shutters

- The shutter closing mechanism is shown in FIGURE 31 and comprises a toothed wheel 480 fixed on the cam shaft 60 145. The wheel has space for eleven teeth, but one tooth is missing. An operating lever 481 is pivoted on the housing as at 482 and carries at one end a pivoted pawl 483 that is urged by a spring 484 into such position as to engage the teeth of the wheel 480. The other end of the lever 481 is pivoted to a link 485 that is fast with a lug 486 which projects from a vertically reciprocable rod 487. The rod may be urged upwardly by a suitable spring (not shown) interconnecting the upper end of the rod and the top wall of the housing. At the lower end of the rod 487 is a pivoted link 488 that is journaled on the crank-shaft 466.

As the crankshaft rotates, the rod 487 is reciprocated vertically and the lever 481 is rocked so as to cause the pawl 483 to engage successive teeth on the wheel 480 and index the shaft 145. Indexing of the shaft 145 will

continue until such time as the space provided by the missing tooth is opposite the pawl, whereupon further rocking of the lever 481 accomplishes nothing. The space on the wheel 480 is so located relatively to the shaft 145 and to the cams 147 thereon that when the tooth space is opposite the pawl 483 the cams will be in their initial positions and all of the shutters will be closed.

Memory devices reset

The final instrumentalities requiring resetting are the strike and spare memory devices. These devices are reset from the crankshaft 466 by means of a connecting rod 476 (FIGURE 48) that is pivoted to toggle links 477 capable of operation by the connecting rod to reciprocate the bar 289 vertically. The bar 289 will be actuated many more times than is required to reset the memory devices, but the lost motion slot 279 in the link 280 prevents undesired adjustment of the memory devices.

Upon the resetting of the memory devices, the apparatus once again is in condition for use to record the scores of the players.

Bypassing an absent player's line

On some occasions one, or possibly both, teams will be understaffed. That is, one or more players of each team may not be present. In such instances, it is desirable that the machine be capable of bypassing the missing players' lines. In apparatus constructed in accordance with the invention, bypassing of an absent player's line on the No. 1 team's scoreboard can be effected by closing a switch 490 (FIGURE 60) whereupon a circuit will be completed to the solenoids 128 and 133 and the cam shaft 118 rotated so as to effect shifting of the scoring mechanism from one line to another in the manner previously described. A similar switch 490a is provided to effect operation of the solenoids 128a and 133a associated with the cam shaft 119. The switches 490 and 490a may be located at any convenient place on the scoreboard housing.

The apparatus described herein is semi-automatic in operation in the sense that manual actuation of the scoring levers is necessary to set the scoring mechanism in operation. The apparatus may be conditioned for automatic operation in conjunction with automatic pinspotters of known kinds, however, by replacing the manual levers L with connections extending to the switches of the pin sensing apparatus on such automatic pinspotters.

The disclosed embodiment is representative of a presently preferred embodiment of the invention but is intended to be illustrative rather than definitive thereof. The invention is defined in the claims.

I claim:

1. Bowling game scoring apparatus comprising a number of pinfall registering devices corresponding in number to the number of frames to be played in said game; operating means connected at the beginning of the game to all of said devices; actuating means connected to said operating means and operable at the conclusion of each frame to actuate said operating means in accordance with the number of pins felled in such frame; normally inactive disabling means for each of said devices operable to disconnect said operating means from said devices in succession as the game progresses from frame to frame; and means connected to said disabling means operable at the conclusion of registering felled pins in each frame to activate the disabling means associated with such frame and disable its registering device.

2. Bowling game scoring apparatus comprising a number of pinfall registering devices corresponding in number to the number of frames to be played in said game; operating means connected at the beginning of the game to all of said devices; actuating means connected to said operating means and operable at the conclusion of each frame to actuate said operating means in accordance with

the number of pins felled in such frame; means for indicating strikes and spares; normally inactive disabling means for each of said devices operable to disconnect said operating means from said devices in succession as the game progresses from frame to frame; means connected to said disabling means normally operable at the conclusion of registering felled pins in each frame to activate the disabling means associated with such frame and disable its registering device; and means interconnecting said disabling means and said strikes and spares indicating means operable in response to operation of the latter to delay activation of said disabling means until said operating means has been operated in accordance with pins felled in sufficient successive frames to cause the registering devices associated with frames in which strikes or spares are to be scored to indicate scores attributable to such strikes or spares.

3. Bowling game scoring apparatus operable to register the score of a player bowling selectively on first and second alleys, said apparatus comprising a number of pinfall registering devices corresponding in number to the number of frames to be played; operating means connected to each of said devices; first actuating means adapted to be connected to said operating means for actuating the latter to register the score attained on said first alley; second actuating means adapted to be connected to said operating means for actuating the latter to register the score attained on said second alley; and shiftable means operatively connected to said first and second actuating means for selectively connecting them to said operating means.

4. Bowling game scoring apparatus comprising a housing having a number of openings therein corresponding to the number of frames to be played in said game; a pinfall registering device supported by said housing adjacent each of said openings; shutter means interposed between said devices and said openings and obscuring all of said devices from view at the beginning of said game; operating means connected to all of said devices at the beginning of said game; actuating means connected to said operating means for actuating the latter at the conclusion of each frame in accordance with the number of pins felled in such frame; means operatively connected to each of said shutter means operable to open said shutter means successively as scoring is completed in the frame associated therewith; and disabling means actuated in response to opening of each shutter means for disconnecting said operating means from the associated registering device.

5. Bowling game scoring apparatus comprising a housing having a number of openings therein corresponding to the number of frames to be played in said game; a plurality of pinfall registering devices supported by said housing one adjacent each opening; operating means connected to each of said devices at the beginning of the game; actuating means connected to said operating means for actuating the latter at the conclusion of each frame in accordance with the number of pins felled in such frame; shutter means interposed between each of said devices and its associated opening and obscuring all of said devices from view at the beginning of the game, means operatively connected to each of said shutter means operable to open said shutter means successively as scoring is completed in the frame associated therewith; means for recording strikes and spares; means interconnecting said strikes and spares recording means and said opening means operable to delay opening of said shutter means in a frame wherein a strike or spare is scored until said operating means has been actuated in accordance with the number of pins felled in sufficient successive frames to cause the registering device associated with said frame to indicate the score attributable to said strike or spare; and disabling means actuated in response to opening of each shutter means for disconnecting said operating means from said associated registering device.

6. Bowling game scoring apparatus comprising a number of rows of pinfall registering devices, each of said rows having as many of said devices as there are frames in said game; a corresponding number of rows of operating means, the operating means of each row thereof being connected at the beginning of said game to all of the devices in the associated row; actuating means connected to the operating means of one of said rows thereof and operable at the conclusion of each frame thereof to actuate said operating means of said one row in accordance with the number of pins felled in such frame; and shift means operable at the conclusion of the actuation of the operating means of said one row to disconnect said actuating means from said one row of operating means and to connect said actuating means to another of said rows of operating means.

7. Bowling game scoring apparatus comprising a number of rows of pinfall registering devices, each of said rows having as many of said devices as there are frames in said game; a corresponding number of rows of operating means, the operating means of each row thereof being connected at the beginning of the game to all of the devices in the associated row; actuating means connected to the operating means of one of said rows thereof and operable at the conclusion of each frame thereof to actuate said operating means of said one row in accordance with the number of pins felled in such frame; a corresponding number of rows of disabling means; means connected to the disabling means in each of said rows for actuating the latter at the conclusion of scoring in any frame of said one row to disconnect said operating means from the registering device associated with such frame; and shift means operable at the conclusion of the actuation of the operating means of said one row to disconnect said actuating means from said one row of operating means and to connect said actuating means to another of said rows of operating means.

8. Bowling game scoring apparatus comprising a number of rows of pinfall registering devices, each of said rows having as many of said devices as there are frames in said game; a corresponding number of rows of operating means, the operating means of each row thereof being connected at the beginning of the game to all of the devices in the associated row; means associated with each row for indicating spares and strikes scored in any frame of such row; actuating means connected to the operating means of one of said rows thereof and operable at the conclusion of each frame thereof to actuate said operating means of said one row in accordance with the number of pins felled in such frame; means connected to said spares and strikes indicating means for operating the latter to record a spare or strike in any frame of said one row; a corresponding number of rows of disabling means; means connected to the disabling means in each of said rows for actuating the latter at the conclusion of scoring in any frame of said one row to disconnect said operating means from the registering device associated with such frame; means operable in response to actuation of said spare and strike indicating means to delay operation of the disabling means associated with a frame of said one row in which a spare or strike is scored until said operating means of said one row has been actuated in accordance with the number of pins felled in sufficient successive frames of said one row to cause the registering device associated with said frame to indicate the score attributable to said spare or strike; and shift means operable at the conclusion of the actuation of the operating means of said one row to disconnect said actuating means from said one row of operating means and to connect said actuating means to another of said rows of operating means.

9. Bowling game scoring apparatus operable to register the scores of a plurality of players of first and second teams, each of said players bowling alternately on first and second alleys, said apparatus comprising a first plurality of rows of pinfall registering devices, there being as

many of such rows as there are players on said first team and each of said rows containing as many of said registering devices as there are frames in said game; a second plurality of rows of pinfall registering devices, there being as many of such rows as there are players on said second team and each of said second plurality of rows containing as many of said registering devices as there are frames in said game; first operating means connected to the registering devices of said first plurality of rows thereof; second operating means connected to the registering devices of said second plurality of rows thereof; first actuating means adapted for connection to said first and second operating means for actuating the latter in accordance with the number of pins felled on said first alley; second actuating means adapted for connection to said first and second operating means for actuating the latter in accordance with the number of pins felled on said second alley; and shiftable means operatively connected to said first and second operating means for selectively connecting them to said first and second actuating means.

10. The apparatus set forth in claim 9 including means operable in response to the connection of said first actuating means to the operating means of one row of either of said plurality of rows of registering devices and simultaneous connection of said second actuating means to the operating means of another row of the same plurality of rows of registering devices to delay operation of one of said first and second actuating means until after the operation of the other of said first and second actuating means has been completed.

11. Bowling game scoring apparatus for registering the score of a player bowling selectively on first and second alleys, said apparatus comprising a housing having ten openings therein, one for each frame of a normal ten frame game; a pinfall registering device supported by said housing adjacent each opening; operating means connected at the beginning of the game to all of said registering devices for operating each of the latter simultaneously; ten shutters, one adjacent each opening, and interposed between said registering devices and said openings to obscure said devices from view; first actuating means adapted for connection to said operating means when said player is bowling on said first alley; second actuating means adapted for connection to said operating means when said player is bowling on said second alley; shiftable means operable selectively to connect said first and second actuating means to said operating means; means connected to each of said actuating means to operate the latter in accordance with the number of pins felled on the associated alley; means adapted for engagement with each of said shutters in succession, beginning with the first, and operable in response to successive operation of said actuating means to open said shutters successively; and disabling means operable in response to opening of each shutter to disable the operating means associated therewith.

12. The apparatus set forth in claim 11 including strike and spare recording means supported by said housing adjacent each of said openings; means supported by said housing for actuating the recorder of means associated with any frame in which said player scores a strike or spare; means operable in response to actuation of said recording means for delaying opening of the shutter associated with the frame in which a spare or strike is scored until said operating means has been operated in accordance with pins felled in sufficient successive frames to cause the registering device associated with any frame in which a strike or spare is scored to indicate the score attributable thereto.

13. Bowling game scoring apparatus comprising a housing having at least two rows of ten openings each therein, there being one opening in each row for each frame of a normal ten frame game; a pinfall registering device supported by said housing adjacent each opening of each of said rows; first operating means connected to the regis-

tering devices of one row thereof for operating the associated devices to indicate a player's score; second operating means connected to the registering devices of the other row thereof for operating the associated devices to indicate another player's score; actuating means supported by said housing and adapted for connection successively to each of said operating means; and means operatively connected to each of said operating means for successively connecting said first and second operating means to said actuating means.

14. Bowling game scoring apparatus comprising a housing having a plurality of rows of openings therein, there being one opening in each row for each frame of a normal ten frame game; a corresponding plurality of rows of pinfall registering devices supported by said housing, there being one such device adjacent each of said openings; a corresponding plurality of rows of operating means supported by said housing, the operating means of each row thereof being connected at the beginning of the game to all of the registering devices in the associated row so as to operate all of the registering devices in the associated row conjointly; actuating means supported by said housing and adapted for connection successively with each of said operating means; shiftable means supported by said housing and successively engageable with each of said operating means for connecting the latter to said actuating means; means connected to said actuating means for actuating the latter and the operating means to which it is connected in accordance with the number of pins felled in any frame of said game, whereby all of the registering devices connected to the actuated operating means are indexed an amount corresponding to the number of pins felled in such frame; and means connected to said shiftable means operable at the conclusion of indexing of the registering devices connected to said actuating means to disconnect said actuating means therefrom and to connect said actuating means to the succeeding row of operating means.

15. Bowling game scoring apparatus comprising a housing having a plurality of rows of openings therein, there being one opening in each row for each frame of a normal ten frame game; a corresponding plurality of rows of pinfall registering devices supported by said housing, there being one such device adjacent each of said openings; a corresponding plurality of rows of operating means supported by said housing, the operating means of each row thereof being connected at the beginning of the game to all of the registering devices in the associated row so as to operate all of the registering devices in the associated row conjointly; actuating means supported by said housing and adapted for connection successively with each of said operating means; shiftable means supported by said housing and successively engageable with each of said operating means for connecting the latter to said actuating means; a corresponding plurality of rows of shutters supported by said housing, there being one shutter adjacent each opening and interposed between the associated registering device and its opening for obscuring said device from view; means connected to said actuating means for actuating the latter and the operating means to which it is connected in accordance with the number of pins felled in any frame of said game, whereby all of the registering devices connected to the actuated operating means are indexed an amount corresponding to the number of pins felled in such frame; a corresponding plurality of shutter opening members, there being one such member adjacent each shutter of each row; means connected to the shutter opening members in the row corresponding to the row of operating means to which said actuating means is connected and operable at the conclusion of the indexing of said devices to operate the shutter opening member at the opening corresponding to the frame of the game being played, the operation of said shutter opening member effecting engagement thereof with said shutter and opening of the latter; disabling means supported by each of

5 said shutter members and operable upon opening thereof to disconnect said operating means from the associated registering devices; and means connected to said shiftable means operable at the conclusion of indexing of the registering devices connected to said actuating means to disconnect said actuating means therefrom and to connect said actuating means to the succeeding row of operating means.

16. Bowling game scoring apparatus comprising a housing having a plurality of rows of openings therein, there being one opening in each row for each frame of a normal ten frame game; a corresponding plurality of rows of pinfall registering devices supported by said housing, there being one such device adjacent each of said openings; a corresponding plurality of rows of operating means supported by said housing, the operating means of each row thereof being connected at the beginning of the game to all of the registering devices in the associated row so as to operate all of the registering devices in the associated row conjointly; actuating means supported by said housing and adapted for connection successively with each of said operating means; shiftable means supported by said housing and successively engageable with each of said operating means for connecting the latter to said actuating means; means connected to said actuating means for actuating the latter and the operating means to which it is connected in accordance with the number of pins felled in any frame of said game, whereby all of the registering devices connected to the actuated operating means are indexed an amount corresponding to the number of pins felled in such frame; and means connected to said shiftable means operable at the conclusion of indexing of the registering devices connected to said actuating means to disconnect said actuating means therefrom and to connect said actuating means to the succeeding row of operating means; totalizing means supported by housing and adapted to be indexed each time any of said registering devices is indexed so as to indicate the total number of pins felled in all frames; indexing means connected to said totalizing means for indexing the latter; and means connected to said indexing means for operating the latter.

17. Bowling game scoring apparatus comprising manipulatable means operable following the bowling by a player in a frame of said game to indicate the number of pins felled in said frame; pinfall registering means for each frame of said game; operating means connected to said pinfall registering means and including an electric circuit for connecting said manipulatable means to the pinfall registering means associated with the frame bowled by said player, said circuit being operable to transmit scoring pulses to said associated pinfall registering means in accordance with the number of pins felled in such frame; and disabling means connected in circuit with said operating means and with said manipulatable means and operable following the transmission of said scoring pulses to said associated pinfall registering means to disconnect said associated pinfall registering means from said operating means.

18. Bowling game scoring apparatus comprising manipulatable means operable following the bowling by a player of each ball in a frame of said game to indicate the number of pins felled in said frame; pinfall registering means for each frame of said game; operating means connecting to said pinfall registering means and including an electric circuit for connecting said manipulatable means to the pinfall registering means associated with the frame bowled by said player, said circuit being operable to transmit scoring pulses to said associated pinfall registering means in accordance with the number of pins felled in such frame; means connected to said manipulatable means for indicating a strike or spare scored in such frame; means connecting said indicating means in circuit with said associated pinfall registering means; disabling means connected in circuit with said operating means and with said manipulatable means and normally operable to disconnect

said associated pinfall registering means from said operating means following the transmission of scoring pulses to said associated pinfall registering means; and means in circuit with said operating means and said indicating means and operable in response to operation of said indicating means to delay operation of said disabling means pending the registering of pins felled by succeeding balls.

19. Bowling game scoring apparatus for registering the scores of a number of players, said apparatus comprising manipulatable means operable following the bowling by any one player of a frame of said game to indicate the number of pins felled in said frame; pinfall registering means for each frame of each player's game; operating means connected to the pinfall registering means associated with each player, said operating means including an electric circuit for connecting said manipulatable means to the pinfall registering means associated with the frame bowled by any one player; said circuit being operable to transmit scoring pulses to the pinfall registering means of any one player in accordance with the number of pins felled in such frame; disabling means connected in circuit with said operating means and with said manipulatable means and operable following the transmission of said scoring pulses to said associated pinfall registering means to disconnect the latter from said operating means; and shifting means in circuit with said manipulatable means operable to connect the latter successively to the pinfall registering means associated with the other players.

20. The apparatus set forth in claim 19 including totalizing means for recording the scores of all of said players; and means in circuit with said totalizing means and with said manipulatable means for operating said totalizing means in accordance with the pins felled in each player's frame.

21. Apparatus as set forth in claim 20 including handicapping means connected to said totalizing means independently of said manipulatable means and operable to operate said totalizing means to cause the latter to indicate a handicap score.

22. The apparatus set forth in claim 19 including means operable by said manipulating means for indicating a strike or spare scored in any frame by any one of said players; and means in circuit with said operating means and said indicating means operable in response to operation of said indicating means to delay operation of said disabling means pending the registering of pins felled by said one of said players with succeeding balls.

23. Bowling game scoring apparatus for registering the score of a player bowling selectively on first and second alleys, said apparatus comprising first manipulatable means associated with said first alley and operable following the bowling of each frame on said first alley to indicate the number of pins felled therein; second manipulatable means associated with said second alley and operable following the bowling of each frame on said second alley to indicate the number of pins felled therein; pinfall registering means for each frame of said game; operating means connected to said pinfall registering means and including electric circuit means for selectively connecting said first and second manipulatable means to the pinfall registering means associated with the frame bowled by said player, said circuit being operable to transmit scoring pulses to said associated pinfall registering means in accordance with the number of pins felled in such frame; and disabling means connected in circuit with said operating means and with the manipulatable means connected to said associated pinfall registering means operable following the transmission of said scoring pulses to said associated pinfall registering means to disconnect the latter from said operating means.

24. The apparatus set forth in claim 23 including means operable by the manipulatable means connected to the associated pinfall registering means for indicating a strike or spare scored in any frame by said player; and means

in circuit with said operating means and said indicating means operable in response to operation of said indicating means to delay operation of said disabling means pending the registering of pins felled by said player with succeeding balls.

5 25. Bowling game scoring apparatus comprising a scoreboard; a control panel having a number of switches mounted thereon for selective actuation in accordance with the number of pins felled in a frame of said game; 10 ten pinfall registering devices supported by said scoreboard, there being one such device for each frame of said game; operating means connected at the beginning of said game to all of said devices for operating them all simultaneously; electric circuit means for connecting any 15 one of said switches in circuit with said operating means for transmitting scoring pulses to said devices in accordance with the number of pins felled in a frame of said game; and disabling means in circuit with said operating means operable to disconnect the latter from each of 20 said devices in succession at the conclusion of scoring in the frame associated therewith.

26. Bowling game scoring apparatus comprising a scoreboard; a control panel having a number of switches mounted thereon for selective actuation in accordance with the number of pins felled in a frame of said game; 25 ten pinfall registering devices supported by said scoreboard, there being one such device for each frame of said game; ten shutters supported by said scoreboard, there being one shutter for each registering device and 30 arranged at the beginning of the game to obscure its associated device from view; operating means connected at the beginning of the game to all of said devices for operating them all simultaneously; electric circuit means for connecting any one of said switches in circuit with 35 said operating means for transmitting scoring pulses to said devices in accordance with the number of pins felled in a frame of said game; means connected with said circuit means and operable to open each of said shutters in succession at the conclusion of registering the pinfall 40 in the frame with which each of said shutters is associated; and disabling means carried by each of said shutters and operable upon opening of the latter to disconnect said operating means from the associated registering device.

27. The apparatus set forth in claim 26 including spare 45 relay means connected to one of said switches for indicating a spare scored in any of the frames of said game; and means in circuit with said spare relay means and said shutter opening means for delaying operation of the latter in response to operation of said spare relay means until 50 the number of pins felled by the first ball in the next succeeding frame is determined.

28. The apparatus set forth in claim 26 including strike 55 relay means connected to one of said switches for indicating a strike scored in any of the frames of said game; and means in circuit with said strike relay means and said shutter opening means for delaying operation of the latter in response to operation of said strike relay means until the number of pins felled by the next two balls is determined.

60 29. Bowling game apparatus for registering the score of a player bowling alternate frames of said game on first and second alleys, said apparatus comprising a first control panel associated with said first alley and having a number of switches mounted thereon for selective actuation in 65 accordance with the number of pins felled in a frame of said game; a second control panel associated with said second alley and having a number of switches mounted thereon for selective actuation in accordance with the number of pins felled in a frame of said game; a scoreboard; ten pinfall registering devices supported by said scoreboard, there being one such device for each frame of said game; operating means connected at the beginning of said game to all of said devices for operating them all simultaneously; first and second electric circuit means 70 connected respectively to the switches of said first and

second control panels and adapted for connection to said operating means; shiftable means operable to connect said operating means alternately to each of said first and second circuit means for transmitting scoring pulses to said registering devices in accordance with the number of pins felled on the associated alley; and disabling means in circuit with the control panel circuit means with which said operating means is connected and operable to disconnect said operating means from the pinfall registering device corresponding to the frame being scored when scoring of said frame is concluded.

30. The apparatus set forth in claim 29 including spare relay means supported by said scoreboard and connectible by said shiftable means to a switch on either of said control panels for indicating a spare scored on either of said alleys; and means in circuit with said spare relay means operable in response to operation thereof to delay operation of said disabling means until the number of pins felled by the next ball is determined.

31. The apparatus set forth in claim 30 including strike relay means supported by said scoreboard and connectible by said shiftable means to a switch on either of said control panels for indicating a strike scored on either of said alleys; and means in circuit with said strike relay means operable in response to operation thereof to delay operation of said disabling means until the number of pins felled by the next two balls is determined.

32. Bowling game scoring apparatus for registering the scores of a number of players constituting a team, said apparatus comprising a control panel having a number of switches mounted thereon for selective actuation in accordance with the number of pins felled by any one of said players in a frame of said game; a scoreboard; a number of lines of pinfall registering devices corresponding to the number of players, each of said lines containing ten such devices; operating means for each line of registering devices and connected at the beginning of the game to all of the devices in such line for operating all of the devices in such line simultaneously; electric circuit means connected to the switches of said control panel; shiftable means connecting the operating means of one of said lines to said circuit means for transmitting scoring pulses to the registering devices in said one line in accordance with the pins felled in a frame of said game; disabling means in circuit with said switches operable to disconnect said operating means of said one line from the pinfall registering device associated with said frame in said one line following the conclusion of scoring in said frame; and means in circuit with said switches operable following the transmission of scoring pulses to the devices in said one line to shift said shiftable means to disconnect the operating means of said one line from said circuit means and to connect the operating means of another of said lines to said circuit means.

33. The apparatus set forth in claim 32 including totalizing means supported by said scoreboard for indicating the score of all players on said team; and means in circuit with said switches for actuating said totalizing means in accordance with the pins felled by each player in each frame of said game.

34. Bowling game scoring apparatus for registering the scores of a number of players constituting a team bowling alternately on first and second alleys, said apparatus comprising a first control panel having a number of switches thereon selectively operable in accordance with the number of pins felled in any frame by any player bowling on the first alley; a second control panel having a number of switches thereon selectively operable in accordance with the number of pins felled in any frame by any player bowling on the second alley; a scoreboard; a number of lines of pin-fall registering devices correspond-

ing to the number of players, each of said lines containing ten such devices; operating means for each line of said devices and connected at the beginning of the game to all of the devices in such line for operating all of the devices in such line simultaneously; first and second similar electric circuit means connected respectively to the switches of said first and second control panels; shiftable means connecting the operating means of the line of the first player on said team to said first circuit means for transmitting scoring pulses to the devices in said first player's line in accordance with the number of pins felled on said first alley in a frame of said game; disabling means in circuit with the switches of said first control panel operable to disconnect said operating means of said first player's line from the device of said first player's line associated with said frame when the scoring in said frame is concluded; means in circuit with the switches of said first control panel operable following the transmission of scoring pulses to the devices in said first player's line to shift said shiftable means to disconnect the operating means of said first player's line from said first circuit means and to connect the operating means of the next player's line to said first circuit means; and means forming part of said shiftable means operable following the transmission of scoring pulses to the devices in the last player's line to connect the operating means of said first player's line to said second circuit means.

35. The apparatus set forth in claim 34 including lock-out relay means in circuit with said first and second circuit means and operable to prevent simultaneous transmission of scoring pulses from said first and second control panels to two or more players' lines on said team.

36. The apparatus set forth in claim 34 including spare relay means for each player's line and connectible by the shiftable means associated therewith to a switch on the control panel to which the operating means of the associated player's line is connected; and means in circuit with said spare relay means operable in response to operation thereof to delay operation of the associated disabling means until the number of pins felled by the next ball of the associated player is determined.

37. The apparatus set forth in claim 34 including strike relay means for each player's line and connectible by the shiftable means associated therewith to a switch on the control panel to which the operating means of the associated player's line is connected; and means in circuit with said strike relay means operable in response to operation thereof to delay operation of the associated disabling means until the number of pins felled by the next two balls of the associated player is determined.

38. The apparatus set forth in claim 34 including totalizing means supported by said scoreboard for registering the scores of all of said players; and means in circuit with the switches of the control panel to which each player's line of operating means is connected and operable to actuate said totalizing means in accordance with the number of pins felled by each player in each frame of said game.
